UNITED STATES PATENT OFFICE.

JOSEPH L. WRIGHT, OF CLEVELAND, OHIO, ASSIGNOR, BY MESNE ASSIGNMENTS, TO
FREDERICK C. STEVENS, OF ATTICA, NEW YORK.

TELEPHONE SYSTEM.

1,145,109.

Specification of Letters Patent. Patented July 6, 1915.

Application filed March 7, 1911. Serial No. 612,788.

To all whom it may concern:

Be it known that I, JOSEPH L. WRIGHT, a citizen of the United States, residing at Cleveland, in the county of Cuyahoga and State of Ohio, have invented certain new and useful Improvements in Telephone Systems, of which the following is a specification, reference being had therein to the accompanying drawing.

10 My invention relates to telephone exchange systems and especially to semi-automatic systems in which incoming calls are distributed among idle operators, who then control selective switches to effect the connections desired.

The general object of this invention is the improvement of systems of the class mentioned in divers particulars which will hereinafter appear.

20 Specific objects may be stated as follows: to prevent a calling line from remaining connected to a defective trunk; to permit several calls from different groups of lines to reach a corresponding number of operators' key sets simultaneously; to permit trunk connections to be effected by a single act on the part of an operator in less time than ordinary numerical selections; to produce trunk connections between automatic 25 and manual switching centers with double supervision by the manual operator; to permit the calling subscriber to free his line and restore the central office apparatus at any time after the calling impulses are started 30 from the operator's key set, but not before; to produce simultaneous drive of primary and secondary switches in a single period of time; to prevent the called subscriber from accidentally releasing the connector, 35 but to permit instantaneous release of the connector when the called line tests busy; to enable an operator to make reverting calls on party lines without tying up unused trunks or switches.

45 My invention is illustrated in the accompanying drawings, in which:

Figure 1 is a skeleton diagram of the complete system, and Figs. 2 to 12^a are detailed diagrams as follows: Fig. 2 shows a subscriber's line and the primary control circuits. Fig. 2^b is a modification of the kick-off switch control. Fig. 3 shows primary

and first selector switch circuits. Fig. 3^a shows a second selector switch circuit. Fig. 3^b is a detail of the release circuit. Fig. 4 55 shows a connector switch circuit. Fig. 5 shows the operator's trunk circuit with key-set control. Fig. 6 shows the operator's key-set and sending machine circuit. Fig. 7 is a subscriber's party-line. Fig. 8 is a detail 60 showing secondary control. Figs. 9 and 10 are complementary figures showing a special first selector switch permanently connected to the operator's trunk circuit for making reverting calls. Figs. 11, 12 and 12^a show 65 the trunk circuits between automatic and manual centers.

In this description I will first outline the system as shown in Fig. 1, then briefly refer to the various pieces of apparatus employed, 70 and finally take up the circuits in Figs. 2 to 12^a inclusive, and explain their operation in detail.

In Fig. 1, each element is marked with the title by which in general it will be 75 designated throughout the case, and enough of the reference letters and numerals are shown for purposes of comparison and to gain a general understanding of the relation of the various parts of the circuits 80 shown in the other diagrams. It may be here stated that for convenience all calls will be assumed to originate at the left hand end or station, and all connections to progress toward the right, the wanted or called 85 subscriber being assumed as the right hand subscriber in every case. Of course, it will be understood that there is no such limitation in practice, but this assumption simplifies description and illustration. In this 90 figure therefore three subscribers are shown at the left hand end of the sheet, whose lines terminate on multiple contacts of three primary selector switches, each of which has a pivoted wiper or contact which can be 95 swept over the line contacts to connect with any one of them. Each of these wipers forms one terminal of a first selector trunk, the other terminal of which is a similar wiper in the first selector switch. The fixed 100 contacts over which these wipers sweep in all the switches are usually referred to as bank contacts, and in mass as "contact banks."

The bank contacts of the first selector switches form the terminals of second selector trunks, each of which is connected to corresponding contacts, that is to say 5 "multiplied", in all the first selectors. At the right hand ends the second selector trunks terminate at wipers of second selector switches, and from the bank contacts of these switches the connector trunks are 10 taken, in multiple as before, to the wipers of connector switches. The banks of these connector switches contain only line terminals, just the same as the primary selectors. At the right hand end of Fig. 1 three subscribers' lines are shown, each with four subscribers' stations connected to it in parallel. These are party lines, so shown for the purpose of illustrating the principle of 15 selective ringing, which forms a part of the system. They need not all be party lines however, nor is it necessary that the subscribers shown on the right of Fig. 1 should be different from those shown at the left. On the contrary, every subscriber's line, 20 in order to have complete service, must be connected to terminals in both the primary selector switches and the connector switches, since it is through the former that the subscriber, when calling reaches the central 25 office, and it is through the connector switches that the central office when calling reaches the subscriber. The connections of 30 a line to primary and connector switches are made in parallel, just as are those of 35 each line to the several switches of either class.

Associated with each connector switch is 40 an auxiliary or ringing selector switch. The wiper of this switch sweeps over contacts connected to several ringing generators, each of which generates a particular distinctive character of current. At the several stations on a party line the bells are 45 designed and adjusted so as to respond selectively and exclusively, each to its own particular kind of current only. At the last stage in a connection, when the wanted subscriber's line has been picked out by the connector switch, and the ringing selector 50 has been set so as to bring into service the proper generator, the wiper of that switch is then automatically connected through the connector to the subscriber's line to ring the bell. At all other times the ringing 55 selector remains disconnected.

The primary selector switches are controlled by the subscribers in calling, through the medium of line relays at the central office which respond to the flow of current 60 in the subscribers' lines, and which when so energized guide and direct the primary switch wipers to their respective line contacts. A calling subscriber therefore gains access to the first selector trunks in the cen-

tral office by his own act alone. In order to continue the connection however, from the first selector trunk to the wanted subscriber, it is necessary to actuate a first selector switch, a second selector switch and a connector switch. The type of switch employed in this system is electromagnetically driven by means of current impulses of predetermined number sent in predetermined groups, which move the switch wipers step by step over the bank contacts. These impulses are supplied, and the switches are controlled, by operators at the central office, who for that purpose are given access through secondary selector switches to the first selector trunks, whereby they are enabled both to receive their orders from the calling subscribers, by way of the primary selectors, and to send impulses to the first selector and succeeding switches, for the purpose of making the desired connection. 75 The secondary selector switches as will presently be seen, are initially responsive to the subscribers' acts in calling. In fact, broadly speaking, their operation is the same as that of the primary selector, the flow of current in a calling subscribers' line and in the first selector trunk connected thereto causing a secondary selector switch wiper to be guided and directed automatically to a contact in its bank which is connected to the first selector trunk in question. 85

In order to select and transmit the proper impulses for line selection I provide each operator with a key-set mounted on a suitable desk, and having associated with it certain 90 signals which guide the operator in the performance of her duties. The key-set in general appearance and arrangement is quite similar to the key board of an adding machine or typewriter, consisting of a number 95 of strips of ten keys each, numbered from one to naught in each vertical row. One of the signals associated with these keys is a calling lamp, which is lighted automatically when the key set becomes connected through 100 the secondary switch to a first selector trunk already connected to a subscriber's line through a primary selector switch. Observing the signal, the operator asks the subscriber for the number wanted, and proceeds 105 to depress the corresponding keys or buttons. She then presses a separate starting key, and groups of impulses, corresponding to the buttons depressed, will thereupon be transmitted through the key-set, through 110 the secondary selector switch and through the first selector trunk to the first selector switch, causing the following operations: (1) The first selector switch is stepped around to the contact of a second selector 115 trunk leading to a second selector switch in the thousands group corresponding to the first digit set up; (2) the second selector

switch is stepped around to select a connector trunk leading to a connector switch of the hundreds group corresponding to the second digit set up, (this particular connector containing terminals of the line wanted); (3 and 4) the connector switch is then stepped around in response to the third and fourth groups of impulses to pick out the terminals of the line wanted; and (5) the associated ringing selector having been set in response to the operation of the impulses, the wanted subscriber's bell is automatically rung.

Reference has been made above to "thousands groups" and "hundreds groups" of circuits. This particular switching system is known as a percentage trunking system. That is to say, the connection between any two lines is effected by successive steps or successive acts of subdivision. For example, in an exchange serving ten thousand subscribers, the second selector switches would be divided into ten groups, through one of which access could be had to the connectors containing lines numbered from 1000 to 1999, through the next, to lines numbered from 2000 to 2999, and so on. Similarly, the connector switches in each thousands group would be divided into ten sub-groups according to their hundreds digit. Through the first of these sub-groups, lines numbered from 100 to 199 could be reached, through the second lines numbered from 200 to 299, and so on. Obviously therefore, access could be had to any desired line by selecting first a second selector of the thousands group in which that line number occurs, and then by means of that selector picking out a connector of the hundreds group in which the line number occurred. That connector would then actually contain terminals of the wanted lines. Of course in practice the wiring between the different groups of switches is quite complicated because of the large number of trunk wires employed to furnish the various combinations required between the switches, but the theory is quite simple, and is well enough illustrated in Fig. 1.

As soon as one of the subscribers at the left of Fig. 1 has become connected in the manner stated with one of the subscribers at the right, it is unnecessary and in fact undesirable for the operator to remain longer in connection with them, and means are provided for automatically cutting off and restoring the secondary selector switch as soon as this condition is brought about. Thereafter all the switches in use between the two subscribers are under their own control, and when they finally hang up their receivers the several switches are automatically restored, the connection is broken, and all parts resume the positions of idleness diagrammatically illustrated in Fig. 1.

It will be noted after reading the foregoing, that portions of the apparatus and circuits at the central office are common to all or a number of subscribers' lines, whereby confusion might arise from simultaneous connection of more than one line to the same trunk, more than one trunk to the same line, or more than one operator to the same trunk. Special provision is made however, to prevent this. At the left of Fig. 1 I have indicated what I call a primary distributing switch and a secondary distributing switch. The first of these contains in its banks testing terminals of the primary switches or first selector trunks. It is actuated in response to the subscribers' calls, and always acts to select and start up an idle switch and trunk for connection with the calling line. There is only one distributing switch for all the primary selector switches serving the same group of subscribers, hence only one switch can be started at a time, and this prevents more than one trunk being connected to the same line. In going to the line, the action of the primary switch is to test over its bank contacts until it reaches a contact which has had its condition changed, due to current flowing in the calling line. If more than one line is calling, the switch will stop at the first one to be reached, and thereafter the distributing switch will start another primary selector to search for the second calling line, whereby it is impossible for more than one line to get on the same trunk.

The secondary distributing switch performs the same functions with respect to the operators' or secondary selector switches, and is actuated also in response to the subscribers' calls, so as to start only one secondary selector switch at a time for any one group of trunks.

As no claims will be made herein to the mechanical features of the apparatus employed, detailed description thereof is unnecessary; and the construction and functioning of the several pieces will be sufficiently understood from the detailed statement of operation hereinafter, read in connection with the following remarks: The unit of the connective system is a one hundred point switch, of the same type as that shown in Letters Patent No. 977,536, granted December 6, 1910, to Charles H. North. The primary and secondary selector switches shown in diagram in Figs. 3, 5 and 9 require a row test wiper on the spindle in addition to those shown in the North patent, but this may be affixed to the spindle in any suitable way, being of course insulated therefrom. The function of this wiper as it is shown at 125 w^{21} and w^{22} in Figs. 3 and 5 respectively, is to pick out the row of contacts in which the individual contacts of a calling line or trunk

- may be found. This is done during the first or rotary motion of the spindle, and when the busy or calling row-contact is found, the switch stops rotating and starts to step up 5 the row designated. The lower or test contacts w^{25} , w^{33} and w^{44} , in Figs. 3 and 5 respectively, then slide up the row of individual test contacts until the particular calling contact is reached, when all motion ceases, 10 and as the connective or talking contacts w^3-w^4 , $w^{30}-w^{31}$ (Figs. 3 and 5) move constantly with the test wipers and are alined thereby, the calling line or trunk is thus accurately selected and connected.
- 15 The relays throughout the system are preferably of the type shown and described in Letters Patent No. 972,634, granted October 11, 1910, to Charles H. North; but any standard relay may be adapted to this 20 service.

The operator's keys employed as shown in Fig. 6 are built in strips, are interlocking, and preferably of the general type shown in Letters Patent No. 955,134, granted April 19, 1910, to John F. Cadell; but obviously other standard interlocking keys 25 may be adapted for this service.

The distributing switches shown at S , S' , S^2 , S^3 , S^7 and S^{11} in Figs. 2, 5, 4, 8 and 9, 30 are single motion step by step electromagnetically driven switches preferably having the driving magnets mounted as a unit on a short frame secured to the contact bank. A convenient form for both the bank and 35 stepping magnet with its armature and pawl, is that shown in the aforesaid North patent. Since only the rotary ratchet and the coöperating rotary magnet are employed, no circuit is taken off through the 40 wipers or spindle, each row or set of contacts in the banks being accompanied by a continuous solid contact constituting a return therefor, and the wipers being in pairs 45 adapted to bridge any unit contact of the set with the common return.

The subscriber's apparatus forms no part 50 of the present invention, except as it is included for completeness in description, and is of any usual or desired type adapted to common battery circuits. The operator's sending machine employed herein is preferably common to the whole exchange and of the type shown in my prior application, Serial No. 402,033, filed November 13, 1907.

55 Referring now to Fig. 2, and bearing in mind the general description of Fig. 1, each line circuit 1-2 is provided with a line relay R' and a cut-off relay R^2 which when energized disconnects the line relay R' and connects the tip and sleeve sides of the line to its multiple bank contacts in the primary and connector switches of its group. The 60 attraction of the armature r^{12} of the relay R' connects ground to the individual test contacts of the primary switches s^4 . The

attraction of armature r^{11} locks the relay R' on shortcircuit to ground through armature r^{23} of relay R^2 , which prevents interference by the subscriber in case he should move his receiver hook. The line relays R' are divided into groups of ten and the windings of each group are connected in multiple to the winding of a relay common to the group, which when energized connects ground to the row contact of the primary 75 switch through the armature r^{21} , thus designating the group of lines calling, while the relay R' designates the particular line in the group.

Each group of one hundred lines is assumed to have access for calling purposes to ten primary selector trunks, such as shown in Fig. 3, and to be accessible for calling through ten connector switches such as shown in Fig. 4. Thus, each line has twenty sets of multiple contacts, ten in primary selector banks, and ten in the connector banks. The primary distributing switch S determines which trunk in the group of ten being idle, shall respond to any particular call in its group of lines; and one of these primary distributing switches is therefore required for each group of one hundred lines, with its ten trunks. Associated with each primary distributing switch S there is a secondary distributing switch S^2 , and a kick-off switch S' . The function of the secondary distributing switch is to pick out an idle operator's circuit and start the same to testing for the group of primary trunks over which the call originates. This can be done because there being only one switch S^2 for each group of one hundred lines, that is to say for each group of ten trunks such as shown in Fig. 3, and 100 since it is convenient to arrange the contacts of each group of ten trunks in one and the same row in the secondary selector switches S^2 (Fig. 5), each secondary distributing switch can therefore be directly 105 identified with its own associated row of primary trunk contacts in each of the secondary selector switches. Furthermore, since each secondary distributing switch S^2 has a 110 number of contacts in its bank, these contacts may be individually connected to several secondary switches, the use of multiples for this purpose in the switches S^2 being thereby avoided, and a great additional 115 advantage gained, in that simultaneous calls 120 may be distributed from different groups such as shown in Fig. 2 to different operator's circuits such as shown in Fig. 5 without interference even when the calls are absolutely simultaneous. The circuits by 125 which this result is attained are shown in Fig. 8 stripped of the detail of the other figures. Assuming an exchange of one thousand lines in which there would be ten 130 groups of lines and trunks, with one sec-

ondary distributing switch S^2 for each group, corresponding contacts s^2 and s^{200} are multiplied in the ten switches and connected respectively to wires 221 and 79 leading to 5 the various secondary switches S^s .

The contacts s^{20} are not multiplied but are wired direct to the row contacts s^{s2} of the secondary switches S^s . Number one switch S^2 belonging to a certain group has its first 10 contact s^{20} wired to number one row contact of the first secondary switch S^s , its second contact s^{20} wired to number one row contact of the second secondary switch S^s , and so on. Number two switch S^2 belonging to another 15 group has its first contact s^{20} wired to number two row contact of the first secondary switch S^s , its second contact s^{20} wired to number two row contact of the second secondary switch S^s and so on. In an 20 exchange of one thousand lines the contacts s^{20} of the tenth switch S^2 are wired to number ten row contacts of the secondary switches S^s .

If in an exchange of one thousand lines simultaneous 25 calls should come in from each group of one hundred lines and ten secondary selector switches S^s were provided, one row contact in each switch S^s would be made active. Without any confusion each 30 switch S^s would test for its active row contact and then find the individual contact in the row. The individual test contacts would be multiplied in a group of secondary switches S^s so that any switch S^s in the 35 group can pick out any trunk belonging to its group.

The relay R^5 has one terminal of its winding connected to the wiper arm w^s of the switch S . When the arm w^s in rotating 40 finds an idle primary switch S^4 the relay R^5 is energized in series with the relay R^{13} (Fig. 3) and opens the circuit of stepping magnet M , thus bringing the switch S to rest. The energizing of the relay R^5 causes 45 the switch S^2 to immediately start to pick out an idle secondary switch S^s . The switch S^4 can be testing for the calling line while the switch S^s is testing for the trunk shown in Fig. 3. The relay R^{13} acts somewhat as 50 the line relay R' , connecting battery to its individual test contacts in the switches S^s .

It will be noticed in the statement of operation hereinafter that the relay R^{13} is not deenergized until the primary switch 55 finds the calling line and the secondary switch S^s finds the trunk connected to that line. By this arrangement all confusion is avoided regardless of which switch performs its functions first.

Referring to Fig. 3, the relay R^{12} is the row test relay, and is energized when the wiper w^{26} finds an active contact, disconnects rotary relay R^{15} and in its place connects vertical relay R^{19} . The relay R^{15} is used in testing for the individual contact as

well as a battery supply relay for the calling subscriber. When energized this relay disconnects the row relay R^{12} . The deenergizing of relay R^{12} disconnects the relay R^{15} from the test wiper w^{25} and connects it to the sleeve wiper w^4 , in series with the cut-off relay R^2 . Relay R^{14} is the tip battery supply relay and controls the release magnets M^3 and M^4 after the first selector switch S^5 has moved off-normal. The relay R^{42} is used for opening the talking circuit while the impulses are being sent to operate the outgoing switches. This relay also with R^{15} 70 jointly controls the relay R^{13} . Relay R^{41} is the test relay having its locking contact r^{413} connected to the test wiper d^{144} . Its circuit is initially closed through the contacts of relay R^{42} and foot springs 144 and 145. After the switch S^5 makes its first vertical 75 step the circuit of this relay is maintained through contacts of relay R^{42} and test wiper w^{147} so long as this wiper encounters busy contacts, which are grounded through other switches. 80

Referring now to Fig. 4, relays R^{22} and R^{23} respond to impulses from the sending machine. Relay R^{23} receives the first set of impulses belonging to the connector and causes the stepping magnet M^{11} of the switch S^7 to step around so as to pick out generator current of the proper character. Operation of relay R^{23} closes the circuit of relay R^{24} whose locking contact r^{241} is connected to the bottom contact of relay R^{22} . Relay R^{23} also closes circuit of relay R^{27} . 90 This latter remains energized until the called party answers or until the calling party hangs up his receiver. In case the called-for line is busy, relay R^{27} will be deenergized by action of test relay R^{29} . Relays R^{24} , R^{27} and R^{29} all have their circuits completed to ground side of battery through test wire 200, contacts s^{200} , w^{147} , 147, r^{413} to ground. When the calling party hangs up his receiver after failing to get his party, 95 100 switches S^4 and S^5 are restored and ground removed from test wire, causing deenergization of any of the relays R^{24} , R^{27} or R^{29} which happen to be locked. The switch S^7 is restored to normal after the called subscriber hangs up his receiver or when the relays R^{22} , R^{27} and R^{24} are deenergized; and just before it reaches its normal position the wiper arm w^s passes over a contact and closes the circuit of the release magnet M^{12} 110 restoring the connector switch S^6 to normal position. Thus the connector switch S^6 has a quick release if the called-for line is busy, and after the called party answers a slow release by switch S^7 which takes care of any 115 accidental shaking of the receiver hook when the called party answers.

Referring to Fig. 5 relay R^{31} is the row test relay and R^{30} the individual test relay. Relay R^{32} is the control relay and corre- 120 125 130

sponds to relay R^{13} (Fig. 3). Relay R^{34} is the signal relay and pulls up in series with relay R^{42} (Fig. 3) after the primary trunk has found the line and the secondary switch S^8 has found the trunk. The operation of this relay closes the circuits of the signal lamp L^3 (Fig. 6), the guard lamp L^2 and the night alarm bell. Relay R^{33} is the listening relay actuated by listening key 10 LK. Operation of this relay deenergizes relays R^{32} and R^{42} and closes circuit of listening lamp L^4 . Relay R^{36} is the starting relay and is energized in series with R^{42} by the key SK. This relay disconnects relay R^{33} and connects the starting cam on the sending machine to stepping magnet M^{15} . It also closes circuit of guard lamp L^2 and disconnects battery from the first five contacts over which wiper ws^{300} sweeps. After 15 arm ws^{300} passes the fifth contact it encounters battery potential and relay R^{35} is energized and connects interrupter I to magnet M^{15} until arm ws^{300} reaches its normal position. Just before switch S^3 reaches normal 20 position, cam springs 167, 168 are closed, completing the circuit of release magnet M^{16} , restoring switch S^3 to its normal position. Relay R^{37} is the trunk start relay and is also used for release in case the 25 calling subscriber has hung up his receiver or if the operator fails to get a response after pressing the listening key. This relay R^{37} is energized by key RK, which also actuates relay R^{36} . These two relays being 30 energized at the same time remove battery connection from the first two contacts over which arm ws^{300} sweeps. In trunk calls, such as to wire chief, toll board, etc., it is only necessary to operate the first selector 35 switch, which with the present sending machine requires only two rotations of the drum. The trunks of this class are wired directly to certain bank contacts of the first selector switches and not to the connector 40 banks, for quick trunk service. After arm ws^{300} passes the second contact the relay R^{35} is energized and operates as before. In case 45 the calling party hangs up his receiver before the operator answers, relay R^{38} is energized in series with resistance coil r when the operator presses the listening key, which connects the tone test to the operator's telephone set, whereupon she presses the trunk start button RK. The first selector switch 50 S^5 upon receiving the first rotary impulse from the sending machine through one of the buttons of the strip K' closes the foot springs 175 and 176. The closure of these springs while relay R^4 is deenergized completes the circuit of release magnets M^3 and M^4 causing the release of switches S^4 and S^5 . Switch S^4 in restoring disconnects relay R^{15} which opens circuits of relays R^{42} , R^{36} and R^{37} . Relays R^{36} and R^{37} falling back 55 connect battery to contacts $1s^{300}$ to $5s^{300}$, en-

ergizing relay R^{35} to restore switch S^3 and S^8 . At any time during the building up of a connection the switches can be restored by the calling party in the manner described.

Referring to Fig. 6, number one key of 70 each strip is connected to the pen on the sending machine which transmits one impulse at each rotation; number two key to that which transmits two impulses, and so on to number ten key which receives ten impulses. Each strip of keys has a common wire connected to one contact of each key in the strip and leading to its proper contact in the banks of the switch S^3 . The order in which these are arranged to transmit impulses in proper sequence is as follows: At the first rotation of the sending machine the first strip of keys (hundreds) is connected to the tip side of trunk through switch arm ws^3 and contact $1s^3$; second rotation, ten test impulses from disk D^{12} sent to sleeve side of trunk through arm ws^{30} and contact $2s^{30}$; third rotation, selective ringing strip K^4 connected to tip side of trunk through arm ws^3 and contact $3s^3$; 80 fourth rotation, keys K^2 (tens) connected to sleeve side through wiper ws^{30} and contact $4s^{30}$; fifth rotation, keys K^3 (units) connected to tip side of trunk through arm ws^3 ; during the fifth rotation and just after the 85 units impulses have been set, a single test impulse is sent to sleeve side of trunk through disk D^{13} , wiper ws^{30} and contact $5s^{30}$; sixth rotation, arm ws^{300} engages contacts connected to battery energizing relay 90 R^{35} . This relay unlocks R^{36} , restores switches S^3 and S^8 , thus disconnecting secondary switch S^8 from the primary trunk in Fig. 3.

The kick-off switch S' in Fig. 2 is provided for the purpose of preventing a defective trunk or operator's circuit from remaining connected to the calling line. In a word, it is a time controlled element started when a call comes in and operating after a predetermined interval longer than the time required for full operation of the switches S^4 and S^8 in Figs. 3 and 5 respectively, so that if the connection from the line in Fig. 2 through Fig. 3 into Fig. 5 is not completed, the switches are restored.

The wipers ws' and ws^{10} are swept over their bank contacts by stepping magnet M' , operated once at each rotation of the sending machine drum by closure of contacts d^{11} . The bank contacts are multiplied as shown, three contacts being left blank in each bank. The multiple contacts over which the wiper ws' sweeps are arranged one step in advance of the corresponding contacts over which wiper ws^{10} sweeps. Relay R^9 is energized when switch S^2 picks out a secondary switch S^8 and partly closes circuit of magnet M' . When the cam on the sending machine closes springs d^{11} the circuit is completed and switch S' moves one 115

step at each rotation of the sending machine. The maximum time for the secondary switch S⁸ to pick out the trunk terminating on the tenth contact in the tenth row would permit about two rotations of the sending machine. As shown by the blank contacts in S' the minimum time element for three rotations has been allowed and the maximum for six, depending upon the position of the 5 wipers of switch S' when relay R⁹ is energized. If wiper ws¹⁰ has just passed multiplied contacts 1s¹⁰ it will then require three steps of switch S' before wiper ws¹⁰ finds battery potential to energize relay R⁷. In 10 this case it would require three more steps for wiper ws' to complete the circuit of relay R⁹. If wiper ws¹⁰ is resting on multiplied contact 1s¹⁰ when relay R⁹ is energized, it will require only three steps of wiper ws', 15 before the circuit of the relay R⁶ is closed. When relay R⁶ operates it places ground on 218, 219, r⁵¹, 31, M to battery, operating magnet M to step wiper ws to the next contact and thereby unlock the relay R⁵ which 20 in turn deenergizes relays R¹¹, R⁹ and R⁸. The operation of relay R⁶ also places ground on 218, 220, ws², 221, r³⁵ (Fig. 5), 122, 171, through release magnet M¹⁶ to battery, causing the release of secondary switch S⁸. 25 If for any reason the secondary switch after it is selected fails to make proper connection with the trunk in Fig. 3 so as to relieve relays R¹³ and R⁵, the kick-off switch will come into play and between three and 30 six rotations of the sending machine cause secondary switch S⁸ to be released and the switch S to pick out another trunk.

A second bank and wiper are shown in switch S in dotted lines, Fig. 2, to indicate 35 the same method of connection, control and release for the primary switches (Fig. 3) by switch S'. The employment of this feature is optional, as in practice if switch S' is left off normal lamp L⁸ quickly attracts 40 attention thereto and localizes the trouble.

Operation: The subscriber at station A desiring a connection lifts receiver R from hook H which bridges his telephone across line wires 1—2, energizing relays R¹ and R³ 45 by way of B, 19, 20, R⁸, 21, R', 22, r²¹, 1, station A, 2, r²², 23, ground to battery. Relay R' locks to ground through r²¹, 24, and r²³, and connects ground to individual test contact c²⁵ through 25 and r¹², while R³ connects ground to row test contact c²⁶ through 50 26 and r³¹ and completes circuit of group lamp L and relay R⁴, the former from B, 19, 27, L, 28, r³², ground to battery, the latter from B, 19, 29, R⁴, 30, r³³, to ground. Lamp 55 L lights, and relay R⁴ completes circuit of stepping magnet M to interrupter I for intermittent energization over the path, B, 19, M, 31, r⁵¹, 32 r⁴¹, 33, I to ground. Magnet M moves switch S step by step 60 until wiper ws engages a contact s connected to relay R¹³ (Fig. 3) of an idle primary selector trunk, whereupon relays R⁵ and R¹³, (Figs. 2 and 3) are energized by current through B, (Fig. 3), 34, 35, 36, r¹⁵¹, 37, R¹³, 38, (38 Fig. 2), s, ws, 39, R⁵, 40, r⁴² to 70 ground. Relay R⁵ opens circuit of magnet M at r⁵¹, locks itself to ground through r⁵² and completes circuit of R¹¹ over path B, 19, 41, R¹¹, 42, R⁵³ and ground. Relay R¹³ locks itself to battery through r¹³¹, 43, r⁴³¹, 75 44, and 34 to B; connects battery to one terminal of relay R¹², through 34, 35, r¹³³, 45, 46, r¹⁵², 47, and 48 and also completes circuit of rotary relay R¹⁸ through r¹³² and interrupter I, so that this relay is energized 80 intermittently, its circuit being: B, 34, 35, r¹³³, 45, 46, r¹⁵², 47, 491, 50, R¹⁸, 51, r¹²¹, 52, r¹³², I to ground. At each actuation of relay R¹⁸ magnet M³ is energized by current from B, 34, 57, contacts 58 of foot step switch F⁴, 85 59, M⁵, 53, r¹⁸¹, ground, stepping primary selector switch S⁴ around until wiper w²⁴ engages row test contact c²⁶ whereupon relay R¹² is energized over circuit B (Fig. 3) 34, 35, r¹³³, 45, 46, r¹⁵², 47, 48, R¹², 49, w²⁶, 90 c²⁶, (Fig. 2) 26, r³¹, ground to battery. Relay R¹² locks itself to ground through r¹²², connects test wiper w²⁵ to sleeve relay R¹⁵ through 54, r¹²³, and 55, and shifts interrupter I from rotary relay R¹⁸ to vertical 95 relay R¹⁹ at r¹²¹, so that R¹⁹ is intermittently energized over the circuit: B, 34, 35, r¹³³, 45, 46, r¹⁵², 47, 491, R¹⁹, 56, r¹²¹, 52, r¹³², I, ground, to battery. At each actuation of relay R¹⁹ vertical magnet M⁶ is energized over the path B, 34, 60, M⁶, 61, r¹⁰¹ to ground, stepping switch S⁴ up until wiper w²⁵ engages individual test contact c²⁵ (Fig. 2) whereupon sleeve relay R¹⁵ is energized over the circuit: B, (Fig. 3), 34, 35, 62, R¹⁵, 105 55, r¹²³, 54, w²⁵, c²⁵, (Fig. 2), 25, r¹² (of relay R'), ground to battery. Relay R¹⁵ connects battery to trunk conductor 7, by way of r¹⁵¹, 63, 64, r¹⁴¹, 65, and resistance r, and at the same time opens the circuit of relay 110 R¹² at r¹⁵². Relay R¹² opens circuit of vertical relay R¹⁹ and magnet M⁶ is deenergized, which permits wiper w²⁵ to stop on contact c²⁵, wipers w⁹ and w⁴ engaging contacts c³ and c⁴, respectively. Tip relay R¹⁴ 115 is now energized through subscriber's telephone in series with R¹⁵. Simultaneously with the selection of the calling line as described, distributing switch S², (Fig. 2) is stepped around in search of an idle secondary selector, by magnet M² in circuit: B, 19, 41, 66, 67, 68, r⁹¹, 69, M², 70, r¹¹¹, 71, I to ground. Switch S² continues to step around until wiper arm ws²⁰⁰ engages a contact 120 s²⁰⁰ connected to an idle secondary selector, whereupon relays R¹⁰ and R³², (Figs. 2 and 5) are energized in series, the circuit being: B, (Fig. 5), 86, springs 73—74 of operator's jack J, 75, springs 76—77 of foot step switch F⁶, 78, R³², 79, through Fig. 3 into Fig. 2, 125 130

- s^{200} , w^{200} , 80, 81, R^{10} , 82, r^{112} to ground. The actuation of relay R^{10} causes the energization of relay R^9 , the circuit being: B, 19, 41, 66, 67, r^{101} , 83, 84, R^9 , 85, r^{113} to ground.
- 5 Relay R^9 locks itself to battery through r^{92} , and opens circuit of magnet M^2 at r^{91} , whereupon switch S^2 comes to rest with wiper arms w^{s^2} , w^{s^20} and w^{s^200} resting on contacts s^2 , s^{20} , and s^{200} , respectively.
- 10 The attraction of armature r^{91} of relay R^9 connects battery to wire 99 which completes part of the row test circuit and the attraction of armature r^{93} completes the circuit of relay R^8 as follows: B, to R^8 , 223, r^{93} to ground. Relay R^8 , grounds wire 80, shunting relay R^{10} out of series with relay R^{32} (Fig. 5) the circuit of the latter relay now going direct to ground by way of wire 80 and armature r^{82} . Relay R^{32} (Fig. 5) completes the circuit of rotary relay R^{30} through interrupter I so that said relay is intermittently energized by current over B, 86, 87, r^{301} , 88, r^{311} , 89, R^{39} , 90, r^{321} , I to ground. Relay R^{32} also connects one terminal of relay R^{30} to ground through 91 and r^{322} , and locks itself to battery through 92, r^{323} , 93, r^{302} , 87, 86, B. Each actuation of relay R^{30} energizes rotary magnet M^{13} through B, 86, 94, M^{13} , 95, r^{391} to ground.
- 15 Magnet M^{13} steps switch S^8 around until wiper w^{s^2} engages contact s^{82} . The first rotary step of the switch S^8 disconnects contacts 76 and 77 of switch F^8 and connects contacts 76 and 290, which opens the initial energizing circuit of relay R^{32} , (that relay, however, remaining energized through its locking circuit) and closes the circuit of off-normal lamp L^7 as follows: B, 86, 73, 74, 75, 76, 290, L^7 to ground. When wiper w^{s^2} engages contact s^{82} the relay R^{31} is energized over the path: B, ground to r^{322} (of relay R^{32}), 91, 96, R^{31} , 97, w^{s^2} , s^{82} , 98, through Fig. 3 into Fig. 2, s^{20} (in switch S^2), w^{s^20} , 99, r^{81} , 68, 67, 66, 41, 19, battery.
- 20 Relay R^{31} locks itself to battery through: 100, r^{312} , 101, 88, r^{301} , 87 and 86, opens circuit of relay R^{39} and closes circuit of relay R^{40} at r^{311} . Relay R^{30} opens circuit of magnet M^{13} at r^{391} , which stops switch S^8 with wiper w^{s^2} engaging contact s^{82} . As circuit of relay R^{40} is completed at r^{311} said relay is intermittently energized through: B, 86, 87, r^{301} , 88, r^{311} , 102, R^{40} , 103, 90, r^{321} , I, ground. Each actuation of relay R^{40} energizes vertical magnet M^{14} through: B, 86, M^{14} , 104, r^{401} , ground. Magnet M^{14} steps switch S^8 up until wiper w^{s^4} engages contact s^{84} , whereupon relay R^{30} is energized through: B, ground to r^{322} (relay R^{32}), 91, R^{30} , 105, w^{s^4} , s^{84} , 45, (45 Fig. 3), r^{138} , 35, 34, battery. Relay R^{30} opens locking circuit of relay R^{32} at r^{302} , also opens circuit of relay R^{40} at r^{301} . r^{401} of relay R^{40} opens vertical magnet M^{14} which stops switch S^8 with wipers w^{s^0} , w^{s^1} , w^{s^3} , and w^{s^4} on contacts s^{80} , s^{81} , s^{83} and s^{84} . (Wiper w^{s^2} is raised off row contacts by first step.) Wiper w^{s^3} engaging contact s^{83} , (Fig. 5) relays R^{34} and R^{42} , (Figs. 5 and 3) are energized through: B, (Fig. 3), 34, 35, 36, r^{151} , 63, 106, R^{42} , 107, (107 Fig. 5), r^{83} , w^{s^3} , 108, r^{313} , 109, r^{351} , 111, 112, R^{44} , 113, r^{331} , 114, r^{361} , 115, r^{352} , 116, r^{322} , ground.
- 25 Relay R^{42} , when actuated, open series circuit of relays R^5 and R^{13} (Figs. 2 and 3) at r^{421} . Relay R^{13} disconnects interrupter I at r^{132} and relay R^5 (Fig. 2) opens circuit of relay R^{11} at r^{52} . Relay R^{11} deenergizing opens circuits of magnet M^2 , relay R^9 and relay R^{10} , while relay R^8 , its circuit opened at r^{93} , opens circuit of stepping magnet M' at r^{81} . This prepares distributing switches, S and S^2 , with their relays, for another call. Relay R^{34} becoming energized closes circuit of night alarm N through: B, 86, 110, 117, 118, r^{341} , 119, N, to ground; closes circuit of guard lamp L^2 (Fig. 6) through B (Fig. 5), 86, 110, 117, 118, r^{342} , 120, 121, (121 Fig. 5), L^2 to ground; closes circuits of service meter E (Fig. 5) through B, armature r^{343} , 122, 242, and magnet of service meter E to ground; 80 and line lamp L^3 (Fig. 6) through B (Fig. 5) r^{343} , 122, 123, (123 Fig. 6), L^3 to ground. The operator, perceiving the signal, depresses listening key LK (Fig. 6) energizing listening relay R^{33} (Fig. 5) through: B, 86, 110, 117, 118, r^{301} , 88, 101, r^{312} , 124, R^{33} , 125, (125 Fig. 6), contacts of key LK, 126 to ground. Relay R^{33} energizing, opens series circuit of relays R^{34} and R^{42} at r^{331} and locks itself to ground through r^{331} , and 114, 100 as previously traced. Relay R^{42} deenergizing, opens circuit of relay R^{41} at r^{421} . Relay R^{33} completes the operator's listening circuit as follows: receiver OR, 127, plug P, tip p, spring j, 128, r^{338} , 129, 131, w^{s^0} , s^{80} , 130, (130 Fig. 3), r^{411} , 133, 9, r^{422} , 7, condenser C', 5, w^3 , c^3 , (Fig. 2), 3, r^{21} , line wire 1, subscriber's telephone, line wire 2, r^{22} , 291, 4, c^4 , w^4 , (Fig. 3), 6, condenser C², 8, r^{423} , 10, 134, r^{412} , 135, (135 Fig. 5), s^{81} , w^{s^1} , 132, 110, 136, r^{332} , 137, coil IC, 138, jack spring j', 136, plug sleeve p', 139, receiver OR.
- 30 Should the calling subscriber hang up his receiver before the operator is connected, tip relay R^{14} (Fig. 3) is deenergized, its circuit being open at the subscriber's switch hook contact, and sleeve relay R^{15} remaining energized in series with cut-off relay R^2 (Fig. 2), energizing circuit of relay R^{38} , (Fig. 5) is completed as follows: B, (Fig. 3) 34, 35, 36, r^{151} , 63, 64, r^{411} , 65, through resistance r, trunk conductor 7, r^{422} , 9, 133, r^{411} , 130 (130 Fig. 5), s^{80} , w^{s^0} , 131, 129, r^{338} , 128, 154, R^{38} to ground. Relay R^{38} energizing, connects operator's tone-test circuit Tt through 155 and 137 to operator's receiver, and the operator being thus notified that the calling subscriber has disconnected, actuates the "release and trunk start" key RK, (Fig. 6) whereupon relay R^{37} (Fig. 130

5) receives current through: B, 86, 110, 156, R³⁷, 157, (157 Fig. 6) key RK to ground. R³⁷ then energizes starting relay R³⁶ in series with relay R⁴² (Fig. 3), through: B, (Fig. 3), 34, 35, 36, r¹⁵¹, 63, 106, R⁴², 107, (107 Fig. 5), s⁸³, w⁸³, 108, r³¹³, 109, r³⁵¹, 111, 141, R³⁶, 140, 158, r³⁷¹, 159, 157 to ground through RK. Relay R⁴² energizes relay R⁴¹ which through armatures r⁴¹¹ and r⁴¹² connects impulse sending wires 130 and 135 to tip and sleeve conductors 9 and 10 respectively. The circuit of relay R⁴¹ is: B, 34, 44, r⁴²¹, 142, R⁴¹, 143, contacts 144 and 145 of foot-step switch F⁵ to ground. Relay R³⁶ being energized, opens the locking circuit of listening relay R³³ at r³⁶¹ and locks itself through 148, r³⁶¹, 115, r³⁵², 116, r³²², to ground; and also establishes a locking circuit for relay R³⁷ through 159, r³⁷¹, 158, 140, 148, r³⁶¹ to ground over the same path traced for locking circuit of relay R³⁶. Armature r³⁶² closes circuit of guard lamp L² (Fig. 6) through: B, (Fig. 5) 86, 110, 117, 149, r³⁶², 150, 121, L² to ground, and armature r³⁶³ partially closes circuit of magnet M¹⁵ so that when cam disk D¹¹ (Fig. 6) closes contacts d¹¹, said magnet is momentarily energized, stepping switch S³ forward one step. The circuit of magnet M¹⁵ is: B, (Fig. 5), 86, 110, 117, M¹⁵, 153, r³⁵³, 152, r³⁶³, starting wire 151, (151 Fig. 6), contacts d¹¹, to ground.

Immediately after switch arm ws³ engages contacts 1s³, a number of ground impulses come from the sending machine over wire 173 (as hereinafter described) by way of contact 1s³, wiper-arm ws³, trunk-conductor 131, w⁸⁰, s⁸⁰, 130, (130 Fig. 3), r⁴¹¹, 174, relay R²¹ to battery and ground. Each actuation of relay R²¹ closes circuit of magnet M⁸ at r²¹¹, which steps the switch S⁵ forward one step, springs 173 and 176 of switch F⁵ being closed at the first rotary step. The closure of springs 175 and 176 energizes release magnets M³ and M⁴ of the primary and first selector switches S⁴ and S⁵, through 106, 177, r¹⁴², 178, 179, M³ and M⁴ in multiple, B. These magnets restore their respective switches to normal position. The circuit of sleeve relay R¹⁵ is now open at w⁴, and its armature r¹⁵¹, opens the series circuit of relays R⁴², and R³⁶ (Figs. 3 and 5). Relay R³⁶ opens at r³⁶¹ the locking circuit of relay R³⁷. As wiper arm ws³⁰⁰ is resting on contact 1s³⁰⁰ and armature r³⁶² of relay R³⁶ is retracted, the retraction of armature r³⁷² of relay R³⁷, closes circuit of relay R³⁷ as follows: B, 86, 110, 117, 149, r³⁶², 163, 161, r³⁷², 293, 1s³⁰⁰, ws³⁰⁰, 164, R³⁵ to ground. Armature r³⁵³ of relay R³⁵ connects one terminal of stepping magnet M¹⁵ to interrupter I for intermittent energization over the path: B, 86, 110, 117, M¹⁵, r³⁵³, 165, I, to ground. Magnet M¹⁵ steps around switch arms ws³, ws²⁰ and ws³⁰⁰ over their respective bank contacts. After wiper arm ws³⁰⁰ leaves contact 2s³⁰⁰ and sweeps over contacts 3s³⁰⁰ to 5s³⁰⁰ relay R³⁵ is kept energized through B, 86, 110, 117, 149, r³⁶², 163, 162, contacts 3s³⁰⁰ to 5s³⁰⁰, ws³⁰⁰ and so on as previously traced. When wiper arm ws³⁰⁰ reaches contact 6s³⁰⁰ the circuit of relay R³⁵ is again changed and said relay is energized while the arm sweeps over contacts 6s³⁰⁰ to 9s³⁰⁰, through: B, 86, 110, 166, 6s³⁰⁰ to 9s³⁰⁰, ws³⁰⁰, 164, and so on as previously traced. When wiper arm ws³⁰⁰ passes off the last contact 9s³⁰⁰ it opens the circuit of relay R³⁵, which disconnects magnet M¹⁵ from interrupter I at r³⁵³, and stops switch S³ with its wiper arms ws³, ws²⁰ and ws³⁰⁰, clear of all contacts. Shortly before switch S³ comes to normal position, contact springs 167 and 168 are momentarily closed by a cam on the switch spindle and release magnet M¹⁶ is energized through: B, 86, 169, 170, M¹⁶, 171, 172, 167, 168, ground. Magnet M¹⁶ restores switch S³ to normal position, ready for another call.

If the calling subscriber remains on the line, the operator, on ascertaining the number wanted sets up the same on her key set, (Fig. 6,) by depressing the key in strip K¹ corresponding to the first digit, that in the strip K² corresponding to the second digit, that in the third strip K³ corresponding to the third digit, and that in the strip K⁴ corresponding to the particular ringing generator to be selected, and then actuates starting key, SK, whereupon starting relay R³⁶ (Fig. 5) is energized in series with trunk cut-off relay R²² (Fig. 3) through: ground, 126, (Fig. 6) key SK, 140, (140 Fig. 5) R³⁶, 141, 111, r³⁵¹, 109, r³¹³, 108, w⁸³, s⁸³, 107, (107 Fig. 3), R⁴², 106, 63, r¹⁵¹, 35, 34, battery to ground. Relay R⁴² opens trunk conductors 9—7 and 10—8 at r⁴²² and r⁴²³, and energizes relay R⁴¹ through: B, 34, 44, r⁴²¹, 142, R⁴¹, 143, contacts 144 and 145 of switch F⁵ to ground. Armatures r⁴¹¹ and r⁴¹² connect the impulse wires 130 and 135 to rotary and vertical relays R²¹ and R²⁰, respectively, while armature r⁴¹³ connects conductor 147 to one terminal of relay R⁴¹ through contact 146. Starting relay R³⁶ (Fig. 5) takes ground off relay R³³ through 114, at r³⁶¹, and locks itself through 148, r³⁶¹ and 115 to ground as previously traced. Armature r³⁶² maintains the circuit of the guard lamp through B, 86, 110, 117, 149, r³⁶², 150, 121, guard lamp to ground, as previously traced. Armature r³⁶³ connects starting wire 151 to stepping magnet M¹⁵ through: B, (Fig. 5) 86, 110, 117, M¹⁵, 153, r³⁵³, 152, r³⁶³, starting wire 151, (151 Fig. 6) contact springs d¹¹, to ground; so that when cam disk D¹¹ (Fig. 6) closes contacts d¹¹, said magnet is momentarily energized, stepping switch S³ forward one step. Immediately after cam D¹¹ (Fig. 6) has passed

under the contacts d^{11} , the number cams D' to D^{10} inclusive, pass under their respective contact springs d' to d^{10} inclusive, the cam D' maintaining the closure of contact d' during one closure of the interrupter contact springs d^1 , the cam D^2 maintaining the closure of its contact springs d^2 during two closures of said interrupter contacts, and so on to the cam D^{10} , which maintains the closure of its contact springs d^{10} during ten closures of the interrupter contact springs.

During the passage of the number cams under their contact springs, ground impulses (corresponding in number to the first digit of the wanted line) are sent over the hundreds impulse wire 173 to the rotary relay R^{21} of the first selector switch S^5 , (Fig. 3). Assuming for example, that the number wanted is 246-3, relay R^{21} will be momentarily energized two times, through: ground, 3, 190, d^2 , 191, 192, 193, k^{12} of strip K' , 173, (173 Fig. 5) $1s^3$, ws^3 , 131, w^{80} , s^{80} , 130 (130 Fig. 3), r^{411} , 174, R^{21} , battery B to ground. Relay R^{21} intermittently energizes magnet M^8 which steps switch S^5 to the second row of contacts through which the connector containing wanted subscriber's line is accessible. At the first rotary step of switch S^5 , contact springs 175-176 are closed, completing the circuit of "off-normal" lamp L^8 through B, 103, 104, L^8 , 105, 106, 176, 175 to ground; also partially closing the release circuit through magnets M^3 and M^4 , hereinafter described. After the number cams have passed under their respective springs cam D^{11} again closes its contacts d^{11} , stepping switch S^3 around to bring its wipers into engagement with the next set of contacts. Wiper arms ws^3 , ws^{30} and ws^{300} of switch S^3 now engage their respective contacts $2s^3$, $2s^{30}$, and $2s^{300}$, and cam D^{12} (Fig. 6) connects test impulse wire 189 through springs d^{12} , conductor 190 and springs d^1 to ground during ten closures of springs d^1 , whereupon vertical relay R^{20} (Fig. 3) is intermittently energized through: ground, d^1 , 190, d^{12} , 189, (189 Fig. 5), $2s^{30}$, ws^{30} , 132, w^{81} , s^{81} , 135, (135 Fig. 3), r^{412} , 199, R^{20} , 196, battery, to ground. Relay R^{20} intermittently closes circuit of magnet M^7 at r^{201} , stepping up wipers w^9 , w^{10} and w^{147} of the first selector switch S^5 to engage contacts c^{13} , c^{14} and c^{200} , respectively, leading to a connector trunk (Fig. 4). At the first vertical movement of the spindle of switch S^5 the circuit of relay R^{21} is opened at contact springs 144 and 145 of switch F^6 , and should the connector trunk (Fig. 4) be busy because of the wipers of another first selector switch resting on the multiples of contacts c^{200} , relay R^{41} would remain energized through B (Fig. 3), 34, 44, r^{421} , 142, R^{41} , 146, r^{413} , 147, w^{147} , c^{200} (Fig. 4) to the multiples of c^{200} and thence through the circuit of the other first selector by way of its wiper w^{147} (as in Fig. 3), 147, r^{413} , ground, to battery.

The armature r^{412} of relay R^{41} , remaining attracted permits the next test impulse to energize vertical relay R^{20} , stepping the wipers up to the next set of contacts, and so on until an idle connector is reached, 70 when, relay R^{41} being deprived of ground, releases its armatures. The armature r^{412} , disconnects impulse wire 135 from the relay R^{20} , stepping switch S^5 with its wipers w^9 , w^{10} and w^{147} on contacts c^{13} , c^{14} and c^{200} , respectively, of the connector trunk (Fig. 4). The impulse wires 130 and 135 are now connected to the tip and sleeve conductors 9 and 10 through armatures r^{411} and r^{412} respectively, and contact c^{200} (Fig. 4) and its multiples are connected to ground through: w^{147} (Fig. 3), 147, and r^{413} . After cam D^{12} (Fig. 6) has passed springs d^{12} , starting cam D^{11} again closes springs d^{11} , steps switch S^3 around to bring its wipers into engagement with the third set of contacts. Wiper arms ws^3 , ws^{30} and ws^{300} now engage contacts $3s^3$, $3s^{30}$ and $3s^{300}$, respectively. The number cams now pass under their respective contact springs for the third time and send impulses, corresponding in number to the desired ringing generator (in this case No. 3), to relay R^{23} (Fig. 4), through: ground, springs d^1 (Fig. 6), 190, d^3 , 198, 203, k^{43} , 197, (197 Fig. 5), $3s^3$, ws^3 , 131, w^{80} , s^{80} , 130, (130 Fig. 3), r^{411} , 133, 9, w^9 , c^{13} , (Fig. 4), 16, r^{261} , 204, R^{23} , 205, B to ground. Each actuation of relay R^{23} energizes magnet M^{11} of switch S^7 , through: B, 206, 208, 209, 210 and 211, 212, 213, M^{11} , 214, 215, r^{231} , to 100 ground. Magnet M^{11} moves switch S^7 forward three steps, bringing wipers ws^7 , ws^{70} and ws^{700} onto contacts $3s^7$, $3s^{70}$ and $3s^{700}$ respectively.

The first actuation of R^{23} energizes R^{24} 105 and R^{27} , the first through: B, 206, 207, 205, r^{233} , 247, R^{24} , 202, 200, c^{200} , w^{147} , (Fig. 3) 147, r^{413} to ground, locking itself to battery through 249, r^{241} , 250, r^{222} , 207; the second relay through: B, r^{232} (of relay R^{232}), 234, 110 230, R^{27} , 235, r^{252} , 236, 202, to ground, locking itself to battery through: 232, r^{271} , 233, r^{291} , 231. Cam D^{11} (Fig. 6), again closing contacts d^{11} moves switch S^3 one step bringing its wipers onto the fourth set of contacts. Wiper ws^{30} now engages contact $4s^{30}$ and the number cams close their respective springs and send impulses to R^{22} (Fig. 4) through: ground, contacts d^1 , (Fig. 6) 190, d^4 , 225, 226, 227, k^{24} of strip K^2 , 224, (224 Fig. 5), 120 $4s^{30}$, ws^{30} , 132, w^{81} , s^{81} , 135, (135 Fig. 3), r^{412} , 134, 10, w^{10} , c^{14} , (Fig. 4) 15, r^{261} , 228, R^{22} , 229, 230, 232, r^{271} , 233, r^{291} , 231, battery to ground. Each actuation of R^{22} energizes magnet M^9 through: B, 206, 208, 237, 238, 239, M^9 , 240, r^{221} , ground. Magnet M^9 moves switch S^6 forward four steps bringing wipers w^{17} and w^{18} onto the fourth row of contacts, in which lie the wanted line contacts.

The first actuation of R^{22} opens the lock- 130

ing circuit of R^{24} at r^{222} . The first rotary step opens springs 210—211 and closes 210—246, which shifts battery lead 209 from M^{12} to M^{10} and lights lamp L^6 by current through: B, 210, 246, 245, 264, 266, r^{253} , 248, L^6 to ground. Cam D^{11} (Fig. 6) again closes contacts d^{11} and sends one impulse over wire 151, actuating switch S^3 to step its wipers onto their fifth set of contacts. After cam D^{11} has passed contacts d^{11} , the number cams again actuate their respective spring contacts sending unit impulses through 241, 131 (Fig. 5), wiper ws^2 , ss^2 , to R^{23} (Fig. 4). Each actuation of relay R^{23} energizes M^{10} through: B, 206, 208, 209, 210, 246, 245, 244, M^{10} , 243, r^{272} , 215, r^{231} , to ground. Magnet M^{10} is actuated six times, stepping wipers w^{17} and w^{18} onto contacts c^{17} and c^{18} (Figs. 4 and 8 respectively). The first actuation of relay R^{23} again energizes R^{24} through r^{233} and R^{24} locks itself and disconnects R^{25} and R^{26} from wipers w^{17} and w^{18} at r^{243} and r^{241} to prevent affecting said relays while the wipers are passing over other line multiples. After the number cams pass their springs, and before cam D^{11} closes its springs, cam D^{12} closes springs d^{12} , sending a single test impulse through 292, 132 (Fig. 5), ss^{30} and ws^{30} , to R^{22} (Fig. 4), whereupon if the wanted line (Fig. 7) is busy, with wipers w^{17} , w^{18} , of another connector switch, or w^3 , w^4 of a primary selector switch, resting on multiples of contacts c^{17} , c^{18} , the test relay R^{29} (Fig. 4) is energized, in the first case through: ground, r^{112} (Fig. 3), 147, w^{147} , r^{200} (Fig. 4), 200, 201, R^{29} , 251, r^{223} , 252, r^{281} , 253, 18, w^{18} , c^{18} , (Fig. 7) to the multiple of c^{18} on which the other connector switch wipers are resting, thence through that connector by way of w^{18} , 18, 253, r^{281} , 252, r^{223} , 259, R^{26} , 260, 261, r^{241} , 250, r^{222} , 207, B to ground; in the second case through: ground, R^{29} , c^{18} , thence through the multiple of c^{18} , on which wiper w^4 , of a primary selector is resting, 294, r^{122} , 55, R^{12} , 62, 35, 34, B, to ground. Relay R^{26} when energized locks itself to battery through 262, r^{291} , connects the busy back B₂ to trunk conductor 16, through r^{292} and 263, and closes the release circuit of S^6 through: B, 206, 208, 209, 210, 246, 245, 264, 265, r^{293} , 207, 269, M^{12} to ground. M^{12} then releases the connector switch S^6 . After this impulse relay R^{22} is deenergized, and completes the restoring circuit of switch S^7 , through: B, r^{222} , 250, r^{241} , 261, 270, r^{273} , 271, r^{251} , 272, 213, M^{11} , 214, r^{272} , 273, ws^{700} , s^{700} , 274, I to ground. Magnet M^{11} is intermittently energized until switch S^7 reaches normal position when its circuit is opened between ws^{700} and s^{700} . The test relay R^{29} remains locked, holding busy-back B₂ on trunk conductor 16, to signal the calling subscriber, (Fig. 2), who then hangs up his receiver, opening circuit of R^{14} (Fig. 3) which energizes and releases magnets M^3 and M^4 of switches S^4 and S^5 through ground, 175, 176, 106, 177, r^{142} , 178, 179, M^3 and M^4 , (in multiple), B, to ground. The switch S^5 in 70 restoring opens the circuit of R^{29} (Fig. 4) at c^{200} and w^{147} (Fig. 3) and the busy-back is disconnected. If the wanted subscriber is not busy, R^{27} remains locked, and after the test impulse R^{22} deenergizes, which energizes R^{26} (Fig. 4) and R^{42} (Fig. 7) in series, through: B, (Fig. 4) r^{222} , 250, r^{241} , 261, 260, R^{26} , 259, r^{223} , 252, r^{281} , 253, 18, w^{18} , c^{18} , (Fig. 7) 255, R^{42} to ground. Relay R^{26} closes trunk conductors 15—17 and 80 16—18 at r^{262} and r^{261} , respectively, while R^{42} (Fig. 7) connects line terminals 256 and 257 to extensions 254 and 255. Simultaneously with the energization of R^{26} and R^{42} , ringing relay R^{28} is connected through: 85 B, r^{222} , 250, r^{241} , 261, 270, r^{273} , 277, r^{242} , 278, R^{28} , interrupter I^2 to ground.

Immediately after the test impulse, cam D^{11} (Fig. 6) causes contacts d^{11} to send an impulse over wire 151, stepping switch S^3 90 (Fig. 5) forward one step bringing its wipers onto the sixth contact set. When ws^{300} engages contact ss^{300} , the restoring relay R^{35} is energized through B, 86, 110, 166, ss^{360} to $9s^{300}$, ws^{300} , 164, R^{35} , to ground. 95 Relay R^{35} opens circuit of R^{36} and R^{42} , (Figs. 5 and 3 respectively) at r^{351} and r^{352} , while r^{353} connects magnet M^{15} for intermittent energization through: B, 86, 110, 117, M^{15} , 153, r^{353} , 165, I to ground. Magnet M^{15} 100 steps switch S^3 forward, holding R^{35} energized through ws^{300} and contacts ss^{300} to $9s^{300}$, until the wipers have reached normal position, as shown. The secondary selector switch S^8 is restored by the cam on the 105 switch S^3 , in passing, and the operator's circuit is ready to receive another call.

Ringing relay R^{28} is intermittently energized by interrupter I^2 to ring subscriber A^3 , (Fig. 7) through circuit: G^3 , 279, $3s^{70}$, ws^{70} , 110 280, r^{282} , 281, 17, w^{17} , c^{17} , (Fig. 7) 254, r^{431} , 256, 282, ringer Q^3 , C^{30} , 283, 257, r^{432} , 258, 255, c^{18} , w^{18} , (Fig. 4) 18, 253, r^{281} , 284, resistance r' , 285, 208, 206, B to ground and generator G^3 . At each energization of relay R^{28} the circuit of lamp L^6 is opened at r^{283} . When the called subscriber A^3 takes down his receiver, he bridges his telephone across the line, and at the next non-ringing interval the circuit of the tip relay R^{25} is 120 closed through: B, (Fig. 4) through R^{26} to c^{18} (Fig. 7), 255, r^{432} , 257, 283, H^{30} , telephone at A^3 , 286, 256, r^{431} , 254, c^{17} , w^{17} (Fig. 4) 17, 281, r^{282} , 287, R^{25} , 288, r^{243} , 275, r^{221} to ground. Relay R^{25} opens circuit of R^{27} at 125 r^{252} , relay R^{27} open circuit of ringing relay R^{28} at r^{272} , and the ringing ceases.

The calling and called subscribers A and A^3 , respectively, are now connected for conversation over the circuit indicated in heavy 130

lines in Figs. 2, 3, 4 and 7. Relay R^{25} connects test contact c^{200} through: c^{200} , 200, 202, 236, r^{252} , to ground side of battery, which renders the trunk busy in case the calling party should hang up first. At the end of the conversation, when calling subscriber A hangs up his receiver the circuit of the tip relay R^{14} (Fig. 3) is opened, whereupon armature r^{142} , falling back, closes the circuit of release magnets M^3 and M^4 of the switches S^4 and S^6 , which return to their normal position. When called subscriber A hangs up his receiver, the circuit of tip relay R^{25} (Fig. 4) is opened, whereupon armature r^{251} , falling back, completes the restoring circuit of switch S^7 , said switch is restored, and when wiper arm w^{87} engages contact 98^7 (which occurs just before the switch reaches its normal position) the circuit of release magnet M^{12} is completed as follows: battery B, 206, 207, 289, w^{87} , 98^7 , 290, 269, M^{12} , ground, to battery. The connector switch S^6 then returns to its normal position.

The foregoing description contemplates an exchange of one thousand lines or less, in which the first selector switches are set directly to the terminals of line connectors containing hundreds groups of line terminals. In an exchange of more than one thousand lines the second selector shown in Fig. 3^a is employed being inserted between the first selector of Fig. 3 and the connector of Fig. 4. The link conductors 371—373 and 372—374, with the third conductor 375 extending from multiple contacts c^9 , c^{10} and c^{107} in the banks of the first selector switches S^5 , to the wipers w^{130} , w^{140} , w^{200} of the second selector switch S^{10} , containing multiple contacts c^{13} , c^{14} , and c^{200} of the connector links shown in Fig. 4. M^{20} and M^{21} are rotary and vertical magnets, R^{50} and R^{51} are repeating relays therefor, M^{22} is release magnet and R^{52} is the test relay. The operation of this link is the same as that of the first selector, depending upon a second set of impulses from the sending machine. When switch S^5 connects with the link of Fig. 3^a, R^{52} is energized through: B, 383, R^{52} , 376, 386, 388, 377, M^{22} , 375, c^{107} , w^{147} , (Fig. 3) 147, r^{413} to ground. M^{22} is low wound, and R^{52} being high wound energizes, opening the link at r^{521} and r^{522} ; connecting 371, r^{521} , 380, R^{50} , 381, 382, 383, B; also connecting 372, 396, R^{51} , 384, normally open at 392—393, and 385 to B. Connection between S^5 and Fig. 3^a is due to ungrounded condition of wipers c^{107} , hence R^{41} is deenergized, but any unused test impulses coming over 10, w^{10} , c^{10} , 372 and 396 will not affect R^{51} or M^{21} because of open circuit. Rotary impulses through 9, w^9 , c^9 and 371 affect R^{50} and rotary magnet M^{20} to rotate spindle of S^{10} to desired hundreds row. The first rotary step closes 390—391, 392—393, cut-

ting on R^{51} , and grounding M^{22} . Test impulses follow through 10, w^{10} , c^{10} , and 372, which start R^{51} and M^{21} to step up wiper w^{200} to test for idle connector trunk in the selected group. So long as grounded or busy contacts are found, R^{52} holds up through: B, 383, R^{52} , r^{522} , 375, w^{200} , c^{200} (Fig. 4) and back through other selector test wiper already in contact, as w^{200} , 375, r^{522} and ground (R^{52} in busy selector circuit being deenergized). Reaching an ungrounded terminal, R^{52} unlocks, grounding w^{200} to make contacts test busy, closing link conductors, and cutting off R^{50} and R^{51} . Release circuit with this additional selector is shown in Fig. 3^b. Release magnets M^3 and M^4 (Fig. 3) are connected in parallel to ground through 179, r^{413} , 147, w^{147} , then (Fig. 3^a) c^{107} , 375, M^{22} , 377, 390, 391 and ground. In Fig. 3^b battery is connected by R^{14} through 178, r^{142} , 177, 176, 175, B. Magnets M^3 , M^4 and M^{22} are energized in parallel when the calling subscriber hangs up. When second selectors are employed as thus described, an additional strip of keys and associated parts must be added to those shown in Fig. 6, for example by duplicating the strip K^1 . The wire therefrom, corresponding to the wires 173, 224, 241, and 197, would then be connected in its proper order to a contact on the switch S^8 (Fig. 5) and said switch adjusted to provide for the extra digits, and the corresponding extra set of test impulses required for the additional link in the building up of a connection.

Fig. 10 shows a special or extra first selector S^{12} , permanently connected with the operator's circuit in Fig. 9, and a master switch to cut it into and out of service for handling reverting calls, wherein one party on a line calls for another party on the same line. The purpose of this selector is for the operator to get control of the connector switch and put it on the line, after which the selector in Fig. 10 is released, leaving only the connector in service, to supply battery current to the talking subscribers. The circuit in Fig. 9 is identical with that of Fig. 5 and operates in the manner previously described. Trunk wires 131 and 132 are connected by wires 346 and 347 to wipers w^{100} and w^{110} of switch S^{12} through normally closed contacts of R^{55} . Wire 108 has a branch 345 to a normally open contact of R^{49} . Cam spring 76 is connected to operator's jack through normally closed contacts of R^{49} . These are the only changes. In Fig. 10 R^{55} is the test relay, R^{54} rotary repeating relay, R^{53} is low-wound and connected to wiper w^{120} through normally closed contacts of R^{55} . M^{18} is the release magnet, actuated when the operator restores key k^7 to normal position, after the selector has moved off-normal. R^{49} is operated when key k^7 is

actuated to close springs L^{37} , disconnecting cam spring 76 from the operator's jack, and preventing actuation of R^{32} , thus rendering the trunk busy. Supervisory lamp L^{12} at 5 key k^7 , notifies the operator when the called party answers.

Operation: The operator receiving a call on any key-set from a party desiring connection with another on his own line, notifies 10 him to hang up his receiver, whereupon he is disconnected in the regular manner. Operator then actuates key k^7 on the special key set; closing circuit of R^{49} through: B, 86, 342, 348, R^{49} to ground. R^{49} disconnects 15 343 from r^{491} rendering key-set busy; also connects battery to w^{83} through: B, 351, r^{492} , 345, w^{83} . This permits energization of R^{36} when the operator presses starting button SK. The closure of springs L^{37} operates 20 R^{55} disconnecting wipers w^{100} and w^{110} , from wires 346 and 347 and connecting relays R^{54} and R^{53} . The operator sets up on her key-set the number of the wanted party and presses the starting key in the regular manner, which operates R^{56} to battery at wiper 25 w^{83} . The first set of impulses operates R^{54} and rotary magnet M^{16} stepping switch S^{12} to the desired row. The test impulses now close circuit of magnet M^{17} , causing switch 30 S^{12} to automatically pick out an idle connector switch in the row. The testing operation is identical with that of Fig. 3. After picking out the idle connector (Fig. 4) impulses are sent in proper order to connect with the wanted line. Armature r^{552} of R^{55} is not normally grounded directly, but through low wound relay R^{53} . When R^{24} , 35 37 in Fig. 4 are operated, they lock to ground through R^{53} , energizing it, which opens circuit of lamp L^{12} at r^{531} . After the called subscriber answers, tip relay R^{25} (Fig. 4) grounds test wire 200, contact c^{200} , w^{120} , 350, r^{552} , 356, R^{53} to ground. This shunts out R^{53} , closing circuit of lamp L^{12} 40 through: ground, 360, 357, r^{531} , 341, L^{12} , 86, B. The operator noticing this signal restores key K^7 to normal position deenergizing R^{49} , which energizes M^{18} through: B, 351, r^{492} , M^{18} , 361 to ground. R^{49} also connects R^{32} 45 through 76-77, rendering the secondary switch active to receive incoming calls. Switch S^{12} being restored leaves the connector switch alone on the line under control of the two parties thereon.

50 Figs. 11, 12 and 12a show circuits, for trunking to a manual exchange. When subscriber A^5 (Fig. 12) takes his receiver he closes circuit of line relay R^{47} which lights line lamp L^{11} . Cut-off relay R^{48} is connected to a third conductor of the answering and multiple jacks J' and J^2 , and when energized opens circuit of line lamp L^{11} . R^{47} is bridged with battery across springs j^8 and j^9 of the jacks. The trunk shown in 55 Fig. 11 terminates at the manual board on

70 plug P' and at the automatic end on multiple contacts in the banks of first selectors. R^{44} is operated when the first selector switch picks out an idle trunk, grounds wire 322 and closes circuit of call signal lamp L^{10} .

75 R^{45} is energized in series with R^{48} when plug P' is placed in jack J' . R^{45} extinguishes calling lamp L^{10} and lights supervisory lamp L^9 . R^{46} is the called subscriber's battery supply relay and is in multiple with R^{47} when plug P' is in jack J' . Jack J^3 is used in connection with magneto toll lines to disconnect battery supply relay R^{46} . When the plug (Fig. 12a) is inserted in jack J^3 springs j^1-j' , and j^2-j^3 are separated, disconnecting R^{46} from P' . Springs j^4 and j^5 are closed, energizing R^{45} as with P' in J' .

80 Operation: On receiving a call for a trunk connection the operator sets up the number and presses the starting trunk button which allows but two rotations of the sending machine to complete the connection. The first selector switch operates in the regular manner and picks out the idle trunk in the row leading to the manual exchange.

85 As soon as an idle trunk is found the test contact and wire 322 are grounded, and current divides through: r^2 , 323, 297, 307, 309, r^{451} , 311, one winding of R^{44} , 315, 325, B'; also: r^2 , 324, 298, 306, 308, r^{452} , 310 the other 90 winding of R^{44} , 315, 325, B'. Its windings being arranged cumulatively, R^{44} energizes and lights lamp L^{10} through: ground, r^{463} , 314, r^{411} , 316, L^{10} , 326, 325, B'. The trunk operator getting this signal throws key K^6 95 to connect her telephone across the trunk at k^{26} . Upon getting the number she tests the called line in the usual manner and inserts P' into J' thereby placing R^{46} and R^{48} in series.

100 R^{48} is low wound and R^{45} comparatively high. Lamp L^9 is in multiple with R^{45} through normally closed contacts of R^{46} . The insertion of P' into J' also lights supervisory lamp L^9 , when ringing key K^6 opens the trunk. After R^{45} is energized R^{44} is held up through r^{442} and r^{443} .

105 After the called subscriber at A^5 takes his receiver R^{46} is energized in multiple with R^{47} , and R^{46} extinguishes lamp L^9 , indicating the answer. On hanging up his receiver the calling subscriber restores the primary and first selector switches as previously described. The first selector switch removes ground from wire 322 deenergizing R^{44} , 110 which lights lamp L^{10} through: ground, r^{463} , 312, r^{442} , 306, 308, r^{452} , 313, r^{441} , 316, L^{10} , 326, 325, B'. The called subscriber hanging up releases R^{46} lighting lamp L^9 through: ground, 325, R^{48} , 330, j^1 , p^8 , 303, r^{461} , 317, L^9 , 326, 325, B'. The operator receiving these signals withdraws P' from J' deenergizing R^{46} and R^{48} . R^{45} extinguishes lamps L^9 and L^{10} . After both parties have hung up and until the operator withdraws 115 the trunk plug the test contact to which wire

120 r^{463} , 312, r^{442} , 306, 308, r^{452} , 313, r^{441} , 316, L^{10} , 326, 325, B'. The called subscriber hangs up releases R^{46} lighting lamp L^9 through: ground, 325, R^{48} , 330, j^1 , p^8 , 303, r^{461} , 317, L^9 , 326, 325, B'. The operator receiving these signals withdraws P' from J' deenergizing R^{46} and R^{48} . R^{45} extinguishes lamps L^9 and L^{10} . After both parties have hung up and until the operator withdraws 125 the trunk plug the test contact to which wire

130 r^{463} , 312, r^{442} , 306, 308, r^{452} , 313, r^{441} , 316, L^{10} , 326, 325, B'. The operator receiving these signals withdraws P' from J' deenergizing R^{46} and R^{48} . R^{45} extinguishes lamps L^9 and L^{10} . After both parties have hung up and until the operator withdraws the trunk plug the test contact to which wire

322 is connected tests busy through: first, ground, r^{463} , 312, r^{443} , 307, 297, 323, r^2 , 322 to test contact; second, ground, r^{463} , 312, r^{442} , 306, 298, 324, r^3 , 322 to test contact.

5 This provision is made in case the operator should fail to take down the connection promptly, and prevents any switch from selecting a connected trunk.

In Fig. 11 the parts to the right of the 10 broken line are located at the manual exchange, and those on the left at the automatic exchange.

Fig. 2^a shows a modification of the kick-off switch arrangement, wherein a third 15 bank is wired up and the contacts controlling wires 218 and 218^x (Fig. 2) are connected directly to the first and third contact banks. I here dispense with relays R² and R³. Wire 80 is placed in direct control 20 of R². In Fig. 5 a cut-off relay R¹⁰⁰⁰ is shown, which is energized through a branch of wire 164, while S³ is restoring, to open wires 131 and 132 as indicated by crosses, and prevent transmission of stray impulses.

25 Having thus described my invention what I claim and desire to secure by Letters Patent is:

1. In a telephone exchange system, a plurality of line circuits, a plurality of line 30 relays each having its windings connected on one side to one of said line circuits and connected in groups on the other side to common return wires, a group relay having its windings connected to each of said 35 group common return wires so that current will flow through the winding of said group relay in series with the winding of any relay in its group when the corresponding line circuit is closed, a link circuit and a 40 primary selector switch constituting a terminal thereof and containing test terminals for the lines divided into groups corresponding to the groups of line relays, and a common test terminal for each of said 45 groups, circuit wires extending from contacts of the individual line relays to the corresponding individual test terminals in said switch, and circuit wires extending from contacts in the group relays to the 50 group or row contacts in the switch, whereby the closing of a line circuit in calling will result in the energization of its individual line relay and of its group relay, to change the potential on its individual test 55 terminal and its group or row terminal in the primary selector switch.

2. In a telephone exchange system, a plurality of line circuits, a plurality of line 60 relays each having its windings connected on one side to one of said line circuits and connected in groups on the other side to common return wires, a group relay having its windings connected to each of said group common return wires so that current will 65 flow through the winding of said group re-

lay in series with the winding of any relay in its group when the corresponding line circuit is closed, a link circuit and a primary selector switch constituting a terminal thereof and containing test terminals for the lines divided into groups corresponding to the groups of line relays, and a common test terminal for each of said groups, circuit wires extending from contacts of the individual line relays to the corresponding individual test terminals in said switch, and circuit wires extending from contacts in the group relays to the groups or row contacts in the switch, together with driving means for said switch, 80 means responsive to the row test for changing the motion of the switch on reaching the group or row of contacts in which the calling line terminal is to be found, and means responsive to the individual test to 85 stop the motion of the switch so as to leave it in connection with the calling line.

3. In a telephone exchange system, a plurality of line circuits, a plurality of line relays each having its windings connected on 90 one side to one of said line circuits and connected in groups on the other side to common return wires, a group relay having its windings connected to each of said group common return wires so that current will 95 flow through the winding of said group relay in series with the winding of any relay in its group when the corresponding line circuit is closed, a link circuit and a primary selector switch constituting a terminal thereof and containing test terminals for the lines divided into groups corresponding to the groups of line relays, and a common test terminal for each of said groups, circuit wires extending from contacts of the individual line relays to the corresponding individual test terminals in said switch, and circuit wires extending from contacts in the group relays to the group or row contacts in the switch, together with electromagnetic 110 actuating means adapted to propel said primary selector switch with respect to the groups or rows only, means responsive to the row test to disable said actuating means, further electromagnetic actuating means 115 then brought into operation to propel the switch with respect to the individual contacts in the selected row, and means responsive to the individual test to disable said actuating means so as to leave the switch in 120 connection with the line calling.

4. In a telephone exchange system, a plurality of line circuits, link circuits for interconnecting the same, automatic switching mechanism responsive to calls over the lines 125 to connect a calling line to an idle link, means for selecting and designating the link to be so connected for each call, and a time controlled element brought into action when a connection is initiated, and adapted in 130

- response to an abnormal condition in the designated link, to advance the selection and substitute another idle link circuit for connection to the calling line.
5. In a telephone exchange system, a plurality of line circuits, a plurality of link circuits for interconnecting the same, a primary selector switch adapted to connect the link circuits to the line circuits when calling.
- 10 a distributing switch associated with a group of line circuits and responsive to current changes in any one of its group to select and render active an idle link circuit, and a time controlled element acting after a predetermined interval in response to an abnormal condition in the designated link, to advance said distributing switch so as to select and designate another link exclusively for connection with the calling line.
- 15 6. In a telephone exchange system, a plurality of line circuits, a plurality of link circuits for interconnecting the same, a primary selector switch adapted to connect each link circuit to the line circuits when calling, a line circuit distributing switch associated with a group of line and link circuits responsive to circuit changes in any line of its group to select and render active an idle link circuit, and a step by step switch
- 20 actuated periodically after the initiation of a call, and adapted after a predetermined number of steps, in response to an abnormal condition of the previously selected link circuit, to advance the distributing switch and
- 25 thereby disable the said link and substitute another idle link for connection with the calling line.
7. In a telephone exchange system, a plurality of line circuits, a plurality of connecting link circuits therefor, a primary selector switch adapted to actuate the same after a circuit when calling, distributing means associated with a group of line and link circuits responsive to circuit changes of any
- 30 one of its group to select and render active an idle link circuit, a step by step switch controlling said distributing means, and a time control element for said step by step switch adapted to connect each link to a line
- 35 predetermined interval, in response to an abnormal condition in the selected link circuit, to further actuate the distributing means.
8. In a telephone exchange system, a plurality of line circuits, a plurality of link circuits for interconnecting the same with primary automatic switches for connecting the links to calling lines, operators' circuits, secondary switching means actuated automatically in response to calls for connecting said operators' circuits to the link circuits, distributing means for selecting an idle link circuit, a time control element actuated at periodic intervals after the selection of an idle link to actuate said distributing means

in response to abnormal conditions in the link or operators' circuits, to disconnect and release the latter.

9. In a telephone exchange system, a plurality of line circuits, a plurality of link circuits terminated at one end in driven primary selector switches containing terminals of the lines, an operator's circuit and a driven secondary switch therefor, containing branch terminals of the link circuits, releasing and restoring means for said secondary switch, distributing means for selecting an idle link, means controlled thereby for driving the associated primary switch to select the line calling, and a time controlled circuit changing element brought into operation after the starting of the primary switch, and acting after a predetermined time in response to an abnormal condition in the primary and secondary connections to disable the actuating means for the primary switch and to actuate the release and restoring mechanism for the secondary switch.

10. In a telephone exchange system, a plurality of line circuits, a plurality of link circuits less in number than the number of lines, primary automatic testing switches for the links, each containing terminals of the lines, driving mechanism for each primary switch, a controlling electromagnet for said driving mechanism, an operator's circuit and a secondary automatic testing switch therefor containing terminals connected to the links, release and restoring mechanism for said secondary switch, a primary distributing switch acting in response to a call over any of the line circuits to select an idle link, circuit connections from the distributing switch to the controlling magnet of each primary switch adapted to render the same active when its link is so selected, and an auxiliary time controlled switch associated with said distributing switch, with circuit connections for the distributing switch and for the release mechanism of the secondary switch, closed by said time control switch after an interval of time has elapsed from the starting of the primary switch which is greater than the time required under normal conditions to complete the primary connection of the selected link with the calling line, and the secondary connection of the operator's circuit with the selected link.

11. In a telephone exchange system, a plurality of line circuits, a plurality of connective links less in number than the number of line circuits, a primary selector switch forming a terminal of each link, containing terminals of the lines, driving mechanism and a controlling magnet therefor for each primary switch and its link, a plurality of operators' circuits less in number than the number of links, a secondary selector switch forming a terminal of each operator's circuit and containing terminals of the links,

driving mechanism and release mechanism for each secondary selector switch, a primary distributing switch responsive to current in the line circuits when calling and containing test terminals connected to the respective controlling magnets of the primary selector switches, means associated with each link for changing the condition of its controlling magnet circuit when the link becomes connected to a line whereby said control circuit will thereafter test busy in the primary distributing switch, a secondary distributing switch also responsive to calls over the line circuits, and containing test terminals connected to individual test circuits associated with the respective secondary selector switches, a time control or kick-off switch associated with the primary and secondary distributing switches, circuit connections therefrom to the actuating means of the primary distributing switches and through the secondary distributing switch to the release mechanism of any secondary selector switch with which the said secondary distributing switch is for the time being associated, and means brought into operation on the selection of an idle link circuit and the starting of its primary selector switch to find a calling line, and acting within a predetermined period thereafter longer than the maximum time required for the complete operation of both the primary and secondary selector switches to actuate the primary distributing switch and the release mechanism of the secondary switch, if their respective functions have not been fully performed.

12. In a telephone exchange system, a plurality of line circuits, a plurality of link circuits less in number than the number of lines, a primary selector switch with driving and control mechanism for each link circuit, multiple terminals for the lines in the several primary selector switches, a plurality of operators' circuits less than the number of links, a secondary selector switch with driving and control mechanism for each operator's circuit, terminals of the links in the secondary selector switches, a primary distributing switch containing test terminals for the controlling means for the primary selector switches, and secondary distributing switches containing three sets of associated terminals, the first set constituting test terminals for the controlling mechanism of the secondary selector switches, the second set constituting terminals for the release mechanism of the secondary selector switches, and the third set constituting terminals for selective test contacts, appearing singly and individually, each in one secondary selector switch bank only, whereby the selection of an idle link and the starting of an idle selector switch, is accompanied by a simultaneous selection

of an idle secondary selector switch and operator's circuit, and the designation in said selecting secondary switch of the group of links or lines with which said secondary switch is to become connected.

13. In a telephone exchange system, a plurality of line circuits, link circuits and primary selector switches, operators' circuits and secondary selector switches, line terminals in the primary selectors and link terminals in the secondary selectors, means in each secondary selector for testing to bring the switch to a particular group of links associated with a particular group of lines, and means associated with each group of lines and responsive to calls over any of the lines in its group, adapted to directly control the corresponding group test in the secondary selector switches.

14. In a telephone exchange system, a plurality of line circuits, a plurality of link circuits, primary selectors for the links containing line terminals, a plurality of operators' circuits, secondary selectors therefor containing link terminals, primary means associated with a group of lines for selecting an idle link, secondary means associated with the same group of lines for selecting an idle operator's circuit, means controlled through said primary means for starting the primary switch of the idle link selected so as to test for the calling line, and means operated through said secondary means for starting the secondary selector switch of the operator's circuit selected, to test for the preselected link.

15. In a telephone exchange system, a plurality of line circuits, a plurality of link circuits, primary selectors for the links containing line terminals, a plurality of operators' circuits, secondary selectors therefor containing link terminals, primary means associated with a group of lines for selecting an idle link, secondary means associated with the same group of lines for selecting an idle operator's circuit, means controlled through said primary means for starting the primary switch of the idle link selected so as to test for the calling line, and means operated through said secondary means for starting the secondary selector switch of the operator's circuit selected, to test for the preselected link, together with means associated with each link for completing its selection by the secondary selector switch.

16. In a telephone exchange system, a plurality of line circuits, link circuits and primary selector switches containing line terminals, operators' circuits and secondary selector switches containing link terminals, primary distributing mechanism for the links, secondary distributing mechanism for the operators' circuits, means for actuating both primary and secondary selector switches initially in response to a call over

a line circuit, and means associated with each link thereafter completing the actuation of the selected secondary selector.

17. In a telephone exchange system, a plurality of line circuits divided into groups, a group of link circuits allotted to each group of lines and terminating in primary selector switches containing talking and test contacts for said lines, a plurality of operators' circuits each terminating in a secondary selector switch containing talking and test contacts arranged in groups and each group connected to a particular group of link circuits, a plurality of group test contacts in each secondary selector switch, each associated with a particular group of link contacts, means for driving a secondary selector switch when actuated, to test first for the group contact, to determine the particular group of link circuits with which the secondary switch is to be connected, and second for the particular individual link in said group, primary and secondary distributing switches associated with each group of lines and the corresponding group of links, means responsive to a call over any line in a group to select an idle link in the corresponding group of links, through the medium of the primary distributing switch of that group, means in the secondary distributing switch for selecting an idle secondary selector switch and its associated operator's circuit, and associated means in the secondary distributing switch becoming active when the idle secondary selector switch has been selected, to produce a test condition with respect to the group contact corresponding to the group of links associated with the group of lines in which the call originates, in that particular secondary selector switch which has been selected, whereby the initial test movements of both the primary and the secondary selector switches are directly controlled from the calling line.

18. In a telephone exchange system, a plurality of line circuits divided into groups, a group of link circuits allotted to each group of lines and terminating in primary selector switches containing talking and test contacts for said lines, a plurality of operators' circuits each terminating in a secondary selector switch containing talking and test contacts arranged in groups and each group connected to a particular group of link circuits, a plurality of group test contacts in each secondary selector switch, each associated with a particular group of link contacts, means for driving a secondary selector switch when actuated, to test first for the group contact, to determine the particular group of link circuits with which the secondary switch is to be connected, and second for the particular individual link in said group, primary and secondary distrib-

uting switches associated with each group of lines and the corresponding group of links, means responsive to a call over any line in a group to select an idle link in the corresponding group of links, through the medium of the primary distributing switch of its group, means in the secondary distributing switch of the same group for selecting an idle secondary selector switch and its associated operator's circuit, and associated means in the secondary distributing switch becoming active when the idle secondary selector switch has been selected, to produce a busy test condition with respect to the group contact corresponding to the group of links associated with the group of lines in which the call originates, in that particular secondary selector switch which has been selected, and in no other, the group contacts in all the secondary selector switches being singly and individually connected to single contacts in the several secondary distributing switches, and not multiplied, whereby several secondary selector switches may be simultaneously actuated in response to simultaneous calls in different groups of lines to select and effect simultaneous connection with the several corresponding groups of trunks.

19. In a telephone exchange system, a plurality of line circuits, a plurality of link circuits for interconnecting the same, a plurality of operators' circuits, automatic switches for connecting the links to calling lines, other automatic switches for connecting the operators' circuits to the links, and means directly responsive to calls over the lines adapted to individualize an idle link circuit and an idle operator's circuit for each of several lines calling simultaneously, whereby simultaneous connection of said lines to a corresponding number of operators' circuits may be effected without interference.

20. In a telephone exchange system, a plurality of line circuits, automatic switches for interconnecting the same, operators' circuits and controlling apparatus for the switches, and means directly and simultaneously responsive to calls over the lines, to effect simultaneous connection of a plurality of lines calling simultaneously to separate operators' circuits without interference.

21. In a telephone exchange system, a plurality of line circuits divided into groups, connective apparatus associated with each group, and operators' circuits common to all the connective apparatus, together with means becoming active in response to simultaneous calls in definite groups of lines, to effect simultaneous and individual connection of the several lines so calling to different operators' circuits without interference.

22. In a telephone exchange system, line circuits, connecting links therefor, a plurality of operators' circuits common to the links, and automatic means for simultaneously effecting the connection of a plurality of simultaneously calling lines to a corresponding plurality of links and operators' circuits without interference.
23. In a telephone exchange system, a plurality of line circuits divided into groups, a plurality of links circuits associated with each group, a plurality of operators' circuits common to the groups of links, and automatic means for simultaneously connecting lines in a plurality of groups calling simultaneously to a corresponding plurality of operators' circuits without interference.
24. In a telephone exchange system, a plurality of line circuits, a plurality of link circuits and a plurality of operators' circuits common to the links, in combination with automatic means for effecting simultaneous connection with simultaneously calling lines without interference.
25. In a telephone exchange system, a plurality of line circuits, a plurality of link circuits, and a plurality of operators' circuits common to the links, automatic switches for interconnecting said links and idle operators' circuits, means for distributing calls among the idle operators' circuits, and time controlled means limiting the period of connection with a selected operator's circuit.
26. In a telephone exchange system, a plurality of line circuits, a plurality of link circuits, and a plurality of operators' circuits common to the links, automatic switches for interconnecting said links and idle operators' circuits, means for distributing calls among the idle operators' circuits, and time controlled means limiting the period of connection with the selected operator's circuit, together with means controlled in the operation of said time controlled means for releasing and restoring a pre-selected operator's circuit and its switching mechanism when the said switching mechanism has not completed its connective operation within the limiting period of time.
27. In a telephone exchange system, line circuits and automatic switching apparatus for interconnecting the same, an operator's circuit with means for connecting the same to said automatic switching apparatus, impulse producing means associated with the operator's circuit, a plurality of impulse selecting devices associated with each of said operator's circuits, branch circuits therefrom equal in number to the number of digits or groups of impulses required for complete actuation of the automatic switching apparatus, and a step by step switch associated with each of said operator's circuits and automatically actuated to connect said branch circuits and thereby the several impulse selecting devices to the operator's circuit and the connected switching apparatus in succession, so as to produce a proper sequence of impulse transmission.
28. In a telephone exchange system, a plurality of line circuits, link circuits and automatic selective switches for interconnecting the lines, an impulse machine adapted to produce current changes in recurring groups or cycles, branch circuits equal in number to the number of groups of impulses or digits to be transmitted to the switches, means for determining the number of impulses in each group, and a step by step switch automatically actuated one step for each cycle adapted to connect said branch circuits to the automatic switches in succession.
29. In a telephone exchange system, a plurality of line circuits, automatic switching apparatus for interconnecting the lines, and means for actuating said switches comprising a machine for producing groups of impulses in recurring cycles, and a step by step switch automatically actuated one step for each cycle, and adapted to change the connection of said machine to the automatic switches so as to transmit impulses thereto in predetermined order and number through a succession of cycles.
30. In a telephone exchange system, a plurality of lines, a switch trunk terminating in an automatic selector switch, an operator's trunk circuit with means to connect it to the switch trunk, a sending machine and a key-set comprising a number of groups of keys corresponding to the number of groups of impulses necessary to control the selector switch and a step by step switch connected with the operator's trunk circuit containing contacts forming the terminals of branch circuits from the respective groups of keys in the key set, and adapted to connect the same to the operator's trunk circuit in proper order and sequence to operate the said selector switch.
31. In a telephone exchange system, a plurality of lines, a switch trunk terminating in an automatic selector switch, an operator's trunk circuit with means to connect it to the switch trunk, a sending machine and a key set comprising a number of groups of keys corresponding to the number of groups of impulses necessary to control the selector switch, and a step by step switch connected with the operator's trunk circuit containing contacts forming the terminals of branch circuits from the respective groups of keys in the key set, and adapted to connect the same to the operator's trunk circuit in proper order and sequence to operate the said selector switch, together with actuating means for said step by step switch.

- switch, and a controlling electromagnet therefor with means to energize the same at proper intervals.
32. In a telephone exchange system, a plurality of lines, a switch trunk terminating in an automatic selector switch, an operator's trunk circuit with means to connect it to the switch trunk, a sending machine and a key set comprising a number of groups of keys corresponding to the number of groups of impulses necessary to control the selector switch, and a step by step switch connected with the operator's trunk circuit containing contacts forming the terminals of branch circuits from the respective groups of keys in the key set, and adapted to connect the same to the operator's trunk circuit in proper order and sequence to operate the said selector switch, together with a pawl and ratchet mechanism for said step by step switch, an actuating magnet therefor, and a circuit for the magnet including a suitable source of current and a pair of contacts controlled in the operation of the sending machine at predetermined intervals.
33. In a telephone exchange system, a plurality of line circuits, a portion of said lines being connected to contacts in automatic switching apparatus, and another portion of said lines being connected to jacks in a manual switchboard, a trunk line extending between the manual switchboard and the automatic switching apparatus, and also terminating in contacts in said automatic switching apparatus, an impulse sending and selecting device adapted to be set so as to transmit a predetermined number of impulses in a predetermined number of groups, for actuating the automatic switching apparatus to select a line circuit having contacts therein, and means for modifying the normal operation of said impulse sender, so as to eliminate one or more groups of impulses from the complete cycle of groups which would otherwise be transmitted, for actuation of the switching apparatus in effecting connection with said trunk line only.
34. In a telephone exchange system, a plurality of line circuits, a portion of said lines being connected to contacts in automatic switching apparatus, and another portion of said lines being connected to jacks in a manual switchboard, a trunk line extending between the manual switchboard and the automatic switching apparatus, and also terminating in contacts in said automatic switching apparatus, an impulse sending and selecting device adapted to be set so as to transmit a predetermined number of impulses in a predetermined number of groups, for actuating the automatic switching apparatus to select a line circuit having contacts therein, and means for modifying the normal transmission of said impulse sender, for actuation of the switching apparatus in effecting connection with said trunk line only.
35. In a telephone exchange system, a plurality of line circuits, a portion of said lines terminating on contacts in an automatic switching equipment arranged for percentage trunking, and another portion of said lines terminating on jacks in the manual switchboard, a trunk line extending between the manual switchboard and the automatic switching apparatus, and terminating in contacts in the first selective unit thereof, an impulse sender with setting means adapted to predetermine a complete cycle of groups of impulses for effecting complete percentage selection of a line circuit through successive units in the switching apparatus, and means adapted when actuated to disable said impulse sender after a portion only of a cycle, in order to transmit impulses to the first or initial unit for trunk selection only.
36. In a telephone exchange system, a plurality of line circuits terminating on contacts in automatic switches, a plurality of contacts in automatic connector switches, a plurality of switch links including the said connector and selector switches adapted to give access thereto by percentage trunking, a trunk line terminating on contacts in said selector switches only, and extending therefrom to a separate switching equipment, electromagnetic means for controlling said selector and connector switches in their movements, an impulse sender adapted to transmit a complete cycle of impulses in proper sequence for any desired number, to work first a selector and then a connector switch, and means for disabling the transmission from said impulse sender at will after the transmission of impulses to a selector only; whereby the selection of the trunk circuit through a selector switch may be effected without loss of time due to the completion of a full cycle of impulses.
37. In a telephone exchange system, a plurality of line circuits divided into groups terminating in different exchange switching equipments, a trunk line extending between said equipments, a selector and a connector switch forming part of one of said equipments, line terminals in the connector switch for line selection, connector terminals in the selector switch for percentage selection, and terminals for said trunk line also in the selector switch, an operator circuit adapted to be connected to the selector switch, a sending machine adapted to furnish groups of impulses in recurring cycles, setting means for determining the transmission of predetermined numbers of impulses for each group of a cycle, switching means automatically actuated for connecting said setting means in proper sequence to the operator.

- circuit and thence to the selector switch, and a manually operated key adapted to disable and restore said switching means after a sufficient number of impulses have been transmitted to actuate a selector switch only, whereby trunk selection may be effected in a fraction of the time required for complete line selection through selector and connector switches.
- 10 38. In a telephone exchange system, a plurality of line circuits divided into groups terminating at different exchange centers, a trunk line between the centers, an automatic switching equipment for one center comprising selector switches and connector switches, line terminals in the connector switches and terminals for said trunk in the selector switch, an operator's circuit and an automatic switch for connecting the same to the selector switch circuits temporarily and individually, a sending machine having impulse circuits and adapted to produce groups of impulses therein in recurring cycles, a selective key set associated with the operator's circuit and comprising a plurality of strips of keys all having their corresponding units connected in parallel on one side to the corresponding impulse circuits of the sending machine, and each strip 30 having a common wire extending on the other side into association with the operator's circuit, a step by step switch connected to the operator's circuit and containing terminals for said common wires from the key strips, an electromagnet for driving said step by step switch, a circuit for said magnet containing a source of current, means for automatically closing said circuit for actuating purposes at recurring intervals in the 40 operation of the sending machine, whereby the common wires of the several key strips are connected separately and in sequence to the operator's circuit, means for automatically closing the magnet circuit for restoring 45 the switch after all the key strips have been connected, and manually operated means for restoring said switch and disconnecting the operator's circuit from the selector switch after a sufficient number of key strips have 50 been connected in sequence to transmit impulses for operating the selector switch alone, whereby selection may be made of the said trunk circuit through the selector switch, and the operator's circuit thereupon disconnected and rendered idle, without completing 55 the full cycle of impulse groups corresponding to the impulse set of key strips.
39. In a telephone exchange system, line circuits, link circuits for interconnecting them, primary selector switches for connecting the link circuits with calling lines, selector and connector switches for connecting the links with wanted lines, an operator's circuit, a secondary selector switch for connecting the 60 same to a link circuit, auxiliary apparatus

associated with the operator's circuit, actuating mechanism and release magnets for all the switches and the auxiliary mechanism, means for starting a primary selector switch in response to a call over a line circuit, means 70 for starting the secondary selector switch to connect the operator's circuit with the link associated with the said primary selector switch, and means normally disabling the several release magnets adapted to be controlled in the use of the operator's apparatus, whereby a line over which a call is initiated will become fully connected to the operator's circuit without regard to the act of the subscriber subsequent to initiating 75 the call.

40. In a telephone exchange system, line circuits, link circuits for interconnecting the same, primary selector switches for connecting the links with calling lines, automatic 85 selective switches for connecting the links with wanted lines, an operator's circuit with controlling apparatus for the selective switches, a secondary selector switch for connecting the operator's circuit with the 90 links, release magnets for all the switches, means normally disabling said release magnets so as to remove the switches from control of a calling subscriber after a call has been initiated, and means controlled by the 95 operator in actuating the selective switches, to render the release magnets operative and place them under control of the calling subscriber, whereby all the apparatus may be released and restored to an idle or inactive condition by the calling subscriber at any time after his line has been identified 100 and the desired connection determined.

41. In a telephone exchange system, line circuits, link circuits for interconnecting the 105 same, primary selector switches constituting answering terminals for the links, selector switches constituting calling terminals for the links, an operator's circuit with controlling apparatus associated therewith for actuating the selector switches, a secondary selector switch for connecting the operator's circuit with the links, means for releasing the several switches, and means normally maintaining the release means inoperative, but actuated in the operation of the selector switches to render the release means operative in response to the act of a calling subscriber.

42. In a telephone exchange system, line 120 circuits, link circuits for interconnecting the same, primary selector switches for connecting the links to calling lines, selector and connector switches for completing connections to wanted subscribers, a release magnet for each primary selector switch, a release magnet for each selector switch, and a release magnet for each connector switch, a source of current, a circuit therefrom to the release magnets of the associated pri- 125

mary selector and first selector switch, a circuit connection from said source to the release magnet of each connector switch, controlling means for the connector release circuit responsive to the action of the first selector switch, controlling means for the release magnets of the primary selector and first selector switches responsive to the act of a calling subscriber, and means associated with the first selector switch normally disabling its release circuit and that of its associated primary selector switch but adapted to render the same operative in the first movement of the first selector.

43. In a telephone exchange system, line circuits, link circuits for interconnecting the same, primary selector switches for connecting the links to calling lines, selector and connector switches for completing connections to wanted subscribers, a release magnet for each primary selector switch, a release magnet for each selector switch, and a release magnet for each connector switch, a source of current, a circuit therefrom to the release magnets of the associated primary selector and first selector switch, a circuit connection from said source to the release magnet of each connector switch, controlling means for the connector release circuit responsive to the action of the first selector switch, controlling means for the release magnets of the primary selector and first selector switches responsive to the act of a calling subscriber, and means associated with the first selector switch normally disabling its release circuit and that of its associated primary selector switch but adapted to render the same operative in the first movement of the first selector, together with operator's controlling apparatus for the selector and connector switches.

44. In a telephone exchange system, line circuits, and means for interconnecting the same comprising the following instrumentalities: a primary selector switch and a first selector switch with a trunk or link circuit interconnecting them, line contacts in the primary selector switch and intermediate trunking contacts in the first selector switch, a connector switch and a trunk or link circuit connecting the same to contacts in the selector banks, line contacts in the connector switch, means for actuating the primary selector switch in response to calls over a line circuit having contacts in said switch, a release magnet for said switch, means for actuating the first selector switch and means for actuating the connector switch each responsive to impulses in predetermined order and arrangement, a release magnet for each of said switches, an operator's circuit with a secondary selector switch containing terminals for the primary and first selector link circuit, actuating means for the secondary selector switch, a release magnet for the same, an impulse sender connected to the operator's circuit, means for predetermining the number and arrangement of impulses to be transmitted therefrom through the operator's circuit, a starting key and means controlled thereby for effecting the transmission of predetermined impulses to the first selector and connector switches, a relay in the primary selector link circuit responsive to the act of a calling subscriber when connected thereto, contacts in said relay included in the circuits of the release magnets of both the primary selector and first selector switches, contacts normally open but closed in the first movement of the first selector switch,

release magnet for the same, an impulse sender connected to the operator's circuit, means for predetermining the number and arrangement of impulses to be transmitted therefrom through the operator's circuit, a 70 starting key and means controlled thereby for effecting the transmission of predetermined impulses to the first selector and connector switches, a relay in the primary selector link circuit responsive to the act of a calling subscriber when connected thereto, contacts in said relay included in the circuits of the release magnets of both the primary selector and first selector switches, contacts normally open but closed in the first movement of the 80 first selector switch, included in the circuit of said release magnets in series with said relay contacts, a relay in the connector link, a circuit for said relay extended through the connector trunk or link into the first 85 selector link, and completed only when the first selector is connected to said connector trunk, and contacts in said connector relay controlling circuit connections for the release magnet of the connector switch. 90

45. In a telephone exchange system, line circuits and means for interconnecting the same comprising the following instrumentalities: a primary selector switch and a first selector switch with a trunk or link circuit interconnecting them, line contacts in the primary selector switch and intermediate trunking contacts in the first selector switch, a connector switch and a trunk or link circuit connecting the same to contacts 100 in the selector banks, line contacts in the connector switch, means for actuating the primary selector switch in response to calls over a line circuit having contacts in said switch, a release magnet for said switch, 105 means for actuating the first selector switch and means for actuating the connector switch each responsive to impulses in predetermined order and arrangement, a release magnet for each of said switches, an 110 operator's circuit with a secondary selector switch containing terminals for the primary and first selector link circuit, actuating means for the secondary selector switch, a release magnet for the same, an impulse 115 sender connected to the operator's circuit, means for predetermining the number and arrangement of impulses to be transmitted therefrom through the operator's circuit, a starting key and means controlled thereby for effecting the transmission of predetermined impulses to the first selector and connector switches, a relay in the primary selector link circuit responsive to the act of a calling subscriber when connected thereto, contacts in said relay included in the circuits of the release magnets of both the primary selector and first selector switches, contacts normally open but closed in the first movement of the first selector switch, 120 means for the secondary selector switch, 125 130

- included in the circuit of said release magnets in series with said relay contacts, a relay in the connector link, a circuit for said relay extended through the connector trunk or link into the first selector link, and completed only when the first selector is connected to said connector trunk, and contacts in said connector relay controlling circuit connections for the release magnet of the connector switch, 5 together with a relay in the connector trunk circuit responsive to the acts of a called subscriber when the connector is associated with his line, and means adapted to shift the control of the release magnet of the connector switch from the first connector relay to said second connector relay when the called subscriber answers, whereby a calling subscriber has no control over the primary and first selector switches until the 10 operator has started the transmission of impulses to actuate the first selector switch, but is able to control the connection thereafter, and to release the same if desired, until the called subscriber answers, after which 15 each of the connected subscribers independently controls the immediate portion of the link circuits connected to his line, and may release the same at will.
46. In a telephone exchange system, line 20 circuits and automatic switches for interconnecting the same comprising selector and connector switches, actuating means for each connector switch, means associated therewith for testing a wanted line, a release 25 magnet for the connector switch adapted to be energized for instant release of the switch in response to action of the test means if the line wanted is found busy, and auxiliary means associated with the connector switch 30 responsive to the act of the called subscriber after he has been connected and answered the call, and adapted to release the connector switch after a predetermined period of time relatively long compared 35 with the time required for test release.
47. In a telephone exchange system, line 40 circuits, automatic switches and links for interconnecting the same including a connector switch and test link circuit, means controlled by a calling subscriber for releasing the connector switch at any time before the called subscriber answers, means for effecting a relatively quick release of the connector switch when the called line 45 tests busy, and means for effecting a relatively slow release of the connector switch in response to the act of the called subscriber after he has answered.
48. In a telephone exchange system, line 50 circuits and automatic switches and link circuits for interconnecting the same including a connector switch and test link circuit, a test relay for the connector switch and a release magnet therefor controlled by the test relay for quick release when a line 55 tests busy, and an auxiliary switch associated with the connector switch with circuit connections to the release magnet for effecting slow release of the connector switch after a predetermined movement of the auxiliary switch only, and means responsive to the act of the called subscriber for controlling said auxiliary switch.
49. In a telephone exchange system, line 60 circuits, automatic switches and links for interconnecting the same including a connector switch and its link circuit, a release magnet for the connector switch, a test relay connected to a wiper in the switch and adapted thereby to be brought into connection with the terminal contact of a wanted line, an auxiliary switch having a step by step motion and adapted to be actuated by impulses through the connector circuit, means for producing independent actuation of said switch in response to the act of a called subscriber after he has answered a call, and a circuit extending from said connector release magnet to the test relay for quick release if the line wanted is busy, and also extended to a contact closed in the last movement of the auxiliary switch for slow release by the called subscriber at the termination of the conversation.
50. In a telephone exchange system, line 65 circuits, and automatic switches and links for interconnecting the same, means for actuating said switches to select a wanted line, means for testing the line wanted to ascertain if it is busy, a quick and slow 70 release mechanism controlled respectively by the test means and by a called subscriber after he has answered the call.
51. In a telephone exchange system, line 75 circuits, and automatic switching apparatus including a line selecting switch with actuating mechanism and release mechanism varying its time of operation in accordance 80 with the variation of line and link conditions during the progress of a connection.
52. In a telephone exchange system, a selecting switch comprising a plurality of contacts, a wiper adapted to be constantly driven thereover in one direction only, and means controlled in the movement of the 85 wiper to automatically drive the same forward into an invariable resting position.
53. A step by step selective switch comprising a pair of wipers secured so as to have unidirectional motion only, a plurality 90 of contacts arranged in the path of one wiper, and a continuous contact in the path of the other wiper, both wipers when in their resting or zero position being disengaged from all contacts, an actuating magnet for the wipers, means for directing current and impulses through said magnet of predetermined number to cause the first wiper to rest upon any desired contact, and a restoring circuit including the other wiper 95

and the coöperating continuous contact, together with an impulse generator adapted to send intermittent impulses through the actuating magnet until the circuit is broken 5 when both wipers become disengaged from their respective contacts.

54. In a telephone exchange system, line circuits and automatic switches for interconnecting the same including a connector 10 switch containing line terminals, an auxiliary switch associated with said connector and having a bank of contacts arranged in the arc of a circle and a contact wiper normally disengaged therefrom, a plurality of 15 ringing generator circuits connected to said contacts, an actuating magnet for the wiper and connections therefrom to the connector switch circuit, a second wiper rigidly connected to the first, a continuous contact for 20 the second wiper, a source of current and a circuit interrupter in the circuit adapted to be closed at one point by said second wiper and its continuous contact whenever the switch is actuated, means for intermittently 25 energizing said actuating magnet in a pre-determined manner to select and connect any desired ringing generator to the connector circuit and therethrough to a wanted line, and means for closing the circuit of the 30 said interrupter for restoring purposes, whereby the wipers will be automatically advanced until they disengage their respective contacts and occupy their normal or zero position.

55. In a telephone exchange system, line 35 circuits and automatic switches for interconnecting the same including a connector, switch containing line terminals, a selector switch containing connector trunk terminals, 40 a release magnet for each selector and a release magnet for each connector switch, a pair of conductors forming a metallic talking circuit for each switch trunk, a third conductor extended and completed through 45 associated contacts from the selector to the connector circuits when connected, a test relay in a connector circuit adapted to be controlled through said third conductor and to control the connector release magnet, and 50 means responsive to the act of a calling subscriber for controlling the release magnet of each selector switch, whereby the connector switch may be released by a test relay if the line wanted is busy, but the test will 55 be maintained on the connector terminals until the calling subscriber has released his line and the selector switch or switches.

56. In a telephone exchange system, line 60 circuits and automatic switches for interconnecting the same including selector and connector switches, a pair of conductors in each switch trunk forming a metallic talking circuit between the switches, a third conductor extended and completed through associated contacts between the switches when

they are connected, means for maintaining a test condition on said third conductor from the selector switch end thereof while the switches are interconnected, a test relay in the connector circuit, an energizing circuit 76 for the same completed through a wiper of the connector switch when in contact with a terminal of a busy line, self-locking contacts in said test relay adapted when it is energized to close a short circuit from its 75 windings through said third conductor, whereby its energization will be maintained as long as the selector and connector switches remain connected, and a busy back signal circuit with contacts also in said test 80 relay adapted to connect said signal circuit to the metallic talking circuit, whereby a calling subscriber will be apprised of the busy condition of the line wanted, and will continue to be so apprised until he releases 85 the selector switch portion of the connection, clearing his line, and severing the third conductor in the switch trunk.

57. In a telephone exchange system, line 90 circuits and automatic switches for interconnecting the same including selector and connector switches, a pair of conductors in each switch trunk forming a metallic talking circuit between the switches, a third conductor extended and completed through 95 associated contacts between the switches when they are connected, means for maintaining a test condition on said third conductor from the selector switch end thereof while the switches are interconnected, a test relay in the connector circuit, an energizing circuit for the same completed through a 100 wiper of the connector switch when in contact with a terminal of a busy line, self-locking contacts in said test relay adapted 105 when it is energized to close a circuit including its windings through said third conductor, together with a release magnet for the connector switch and a circuit connection therefor controlled by contacts in the test 110 relay and a busy signal device also controlled by the test relay, whereby when a line tests busy the connector switch will be at once released and restored to its zero position, the busy signal will be transmitted 115 to the calling subscriber as long as he fails to clear out, and the busy test will be maintained on the connector trunk terminals in the selector switches until the selector or calling end of the connection is released. 120

58. In a telephone exchange system, line 125 circuits and automatic switches for interconnecting the same including selector and connector switches, a pair of conductors forming a metallic talking circuit for each switch trunk, a third conductor associated therewith, extending from the selector into the connector circuits, means for maintaining a test condition on the selector end of said third conductor as long as the switches 130

are interconnected, release magnets for the several switches, a connector control relay in the connector circuit with contacts controlling the connector release, and with 5 windings connected to said third conductor, and means in the selector trunk circuits responsive to the acts of calling subscribers for energizing the selector release magnets, whereby a connection may be cleared out, 10 and the switches restored at any time after initiation and before the called subscriber has answered by the act of the calling subscriber directly releasing the selector end of the connection and indirectly the connector 15 end through the severance of the third conductor between the switches, and a consequent deenergization of the connector control relay.

59. In a telephone exchange system, line 20 circuits and automatic switches for interconnecting the same including selector and connector switches, a pair of conductors forming a metallic talking circuit for each switch trunk, a third conductor associated 25 therewith, extending from the selector into the connector circuits, means for maintaining a test condition on the selector end of said third conductor as long as the switches are interconnected, release magnets for the 30 several switches, a relay in the connector circuit with contacts controlling the connector release, and with windings connected to said third conductor so as to be energized by current therethrough, and means in the 35 selector trunk circuits responsive to the acts of calling subscribers for energizing the selector release magnets, together with a second relay in the connector circuit responsive to current flow in the called subscriber's 40 line, and normally closed connections through contacts in said relay to the connector release mechanism and to said first or control relay, whereby the control relay becomes deenergized, and the control of the connector 45 switch is given to the called subscriber after he has answered the call.

60. In a telephone exchange system, line 50 circuits and automatic switches for interconnecting the same comprising selector and connector switches and trunk circuits therefor means for transmitting impulses through the selector trunks to operate a connector switch, actuating electromagnets for said connector, trunk relays therefor, battery 55 supply relays for the called line and a control relay having contacts controlling the circuits of the said actuating magnets and battery feed relays, adapted to be energized and deenergized once during the transmission of each successive group of impulses, disconnecting said battery supply relays, and rendering the actuating magnets active in proper sequence.

61. In a telephone exchange system, line 60 circuits, automatic switches and switch

trunks for interconnecting the same, including a connector switch and trunk coöperating with wanted line terminals, actuating means for the switch, a cut-on relay included in the release circuit of the switch, a ringing 70 relay with energizing means therefor, contacts in said cut-on relay included in the circuit of said ringing relay, means for energizing said cut-on relay in response to the first actuating impulses entering the connector trunk circuit, locking means for maintaining said relay energized thereafter as long as a calling subscriber is associated 75 with the connector trunk and is not yet connected with the wanted subscriber, actuating 80 relays, battery supply relays for the called line, a control relay with contacts included in the circuits of said actuating and battery supply relays, and also in the circuit of said ringing relay, the whole so arranged that during effective transmission of actuating impulses both the cut-on relay and the control relay remain energized, and the ringing relay and subscriber's battery supply 85 relay circuits are held open, on the cessation of the actuating impulses the control 90 relay is deenergized, the ringing relay circuit is closed, and the supply relays placed in condition to respond to the act of the called subscriber in answering, and finally when the 95 called subscriber has answered, the cut-on relay is deenergized, the ringing circuit finally broken, and the release circuit placed in operative condition, subject to control by one of the said supply relays.

62. In a telephone exchange system, line 100 circuits and automatic switching apparatus including a connector trunk and switch containing line terminals, actuating trunk magnets and switches as required to produce co-operation, a ringing relay for said trunk, a control relay and a cut-on relay, means for energizing said cut-on relay continuously during the actuation of the connector switch in selecting a wanted line, means for energizing said control relay at intervals to shift the circuits of the said actuating trunk magnets and relays as required to produce their proper co-operation, and a circuit for said 105 ringing relay jointly controlled by said control and cut-on relays.

63. In a telephone exchange system, line 110 circuits terminating in an automatic switching center, and other line circuits terminating in a manual switching center, a trunk 115 line extending between the two centers and terminating at the manual center in a manually operated connection terminal adapted to coöperate with line terminals, selective switches in the automatic center containing 120 multiple terminals of the trunk line, including test terminals, a pair of signal devices associated with the manual trunk terminal, means controlled by the connection of an 125 automatic switch with the trunk for display- 130

- ing one of said signals, and means responsive to the act of a connected manual subscriber for displaying the other signal, whereby the trunk operator at the manual center is enabled to exercise double supervision over the trunk connection. 5
64. In a telephone exchange system, line circuits terminating in an automatic switching center, and other line circuits terminating in a manual switching center, a trunk line extending between the two centers, and terminating at the manual center in a manually operated connection terminal adapted to co-operate with line terminals, selective switches 10 in the automatic center containing multiple terminals of the trunk line, including test terminals, a pair of signal devices associated with the manual trunk terminal, means controlled by the connection of an automatic switch with the trunk for displaying one of said signals, and means responsive to the act of a connected manual subscriber for displaying the other signal, whereby the trunk operator at the manual center is enabled to 15 exercise double supervision over the trunk connection, together with means whereby the switch controlled signal is rendered inert during the continuance of the connection for conversation. 20
65. In a telephone exchange system, an automatic switching center and a manual switching center with a trunk extending between them, selective switches at the automatic center containing multiple sets of three 25 terminals each for the trunk, a manually operated terminal for the trunk adapted to co-operate with line terminals at the manual switch center, means controlled in the connection of the automatic switch to the trunk 30 to maintain a test condition on the third or test contact of each set in all the switches, and means controlled in the connection of the manual trunk terminal for maintaining said test condition irrespective of the 35 switches, whereby a trunk will test busy to all of the switches in whose banks it has terminals, so long as it remains connected at either end. 40
66. In a telephone exchange system, automatic exchange switching apparatus including a selector switch having talking and test wipers, means for maintaining test potential on the test wiper while the switch is connected, a trunk line extending therefrom to a manual exchange and terminating in a manually operated connective terminal with line terminals in said exchange adapted to co-operate therewith, a pair of talking contacts and a test contact for the 45 trunk in the said first selector switch banks, a circuit extended through the trunk line from said test terminal to the manual exchange, and a relay associated with the manual trunk terminal and controlled in the 50 use thereof, adapted to maintain test potential through said circuit on said test terminal while the manual trunk terminal remains connected to a line at the manual exchange. 55
67. In a telephone exchange system, an automatic exchange and a manual exchange with a trunk line extending between them, calling terminals for the trunk in automatic switches at the first exchange, a manual connective terminal for the trunk at the second exchange, a pair of signal devices associated with said manual terminal, a pair of relays controlling the circuits of said signals, means whereby one of said relays is energized over a circuit including a portion of the trunk and an automatic switch when connected thereto, and means whereby the other relay is energized through a circuit including another portion of the trunk and contacts of the manual terminal thereof. 60
68. In a telephone exchange system, an automatic exchange and a manual exchange, and a two-wire trunk line extending between them having multiple pairs of contacts in switch banks at the automatic exchange forming terminals of the talking circuit, and multiple single contacts associated therewith in the same switch banks, forming test terminals, a parallel or phantom circuit for said test terminals extended over both sides of the trunk to the manual end thereof, and means for imposing test potential on the test terminals over said phantom circuit. 65
69. In a telephone exchange system, an automatic exchange and a manual exchange, and a two-wire trunk line extending between them having multiple pairs of contacts in switch banks at the automatic exchange forming terminals of the talking circuit, and multiple single contacts associated therewith in the same switch banks, forming test terminals, a parallel or phantom circuit for said test terminals extended over both sides of the trunk to the manual end thereof, and means for imposing test potential on the test terminals over said phantom circuit, said means being controlled by the use of the manual connective terminal of the trunk. 70
70. In a telephone exchange system, an automatic exchange and a manual exchange with a trunk line extending between a pair of contact terminals and a test terminal for the trunk in the banks of an automatic switch at the first exchange, a manually operated terminal for the trunk at the second exchange, an advance signal associated with said manual terminal, a relay controlling said signal, a circuit for said relay extending from the relay at the manual end of the trunk to the third or test contact thereof at the first exchange, means at the automatic exchange for energizing said relay over said circuit when connection is of 75 80 85
71. In a telephone exchange system, an automatic exchange and a manual exchange with a trunk line extending between a pair of contact terminals and a test terminal for the trunk in the banks of an automatic switch at the first exchange, a manually operated terminal for the trunk at the second exchange, an advance signal associated with said manual terminal, a relay controlling said signal, a circuit for said relay extending from the relay at the manual end of the trunk to the third or test contact thereof at the first exchange, means at the automatic exchange for energizing said relay over said circuit when connection is of 80 85 90
72. In a telephone exchange system, an automatic exchange and a manual exchange with a trunk line extending between a pair of contact terminals and a test terminal for the trunk in the banks of an automatic switch at the first exchange, a manually operated terminal for the trunk at the second exchange, an advance signal associated with said manual terminal, a relay controlling said signal, a circuit for said relay extending from the relay at the manual end of the trunk to the third or test contact thereof at the first exchange, means at the automatic exchange for energizing said relay over said circuit when connection is of 85 90 95
73. In a telephone exchange system, an automatic exchange and a manual exchange with a trunk line extending between a pair of contact terminals and a test terminal for the trunk in the banks of an automatic switch at the first exchange, a manually operated terminal for the trunk at the second exchange, an advance signal associated with said manual terminal, a relay controlling said signal, a circuit for said relay extending from the relay at the manual end of the trunk to the third or test contact thereof at the first exchange, means at the automatic exchange for energizing said relay over said circuit when connection is of 90 95 100
74. In a telephone exchange system, an automatic exchange and a manual exchange with a trunk line extending between a pair of contact terminals and a test terminal for the trunk in the banks of an automatic switch at the first exchange, a manually operated terminal for the trunk at the second exchange, an advance signal associated with said manual terminal, a relay controlling said signal, a circuit for said relay extending from the relay at the manual end of the trunk to the third or test contact thereof at the first exchange, means at the automatic exchange for energizing said relay over said circuit when connection is of 95 100 105
75. In a telephone exchange system, an automatic exchange and a manual exchange with a trunk line extending between a pair of contact terminals and a test terminal for the trunk in the banks of an automatic switch at the first exchange, a manually operated terminal for the trunk at the second exchange, an advance signal associated with said manual terminal, a relay controlling said signal, a circuit for said relay extending from the relay at the manual end of the trunk to the third or test contact thereof at the first exchange, means at the automatic exchange for energizing said relay over said circuit when connection is of 100 105 110
76. In a telephone exchange system, an automatic exchange and a manual exchange with a trunk line extending between a pair of contact terminals and a test terminal for the trunk in the banks of an automatic switch at the first exchange, a manually operated terminal for the trunk at the second exchange, an advance signal associated with said manual terminal, a relay controlling said signal, a circuit for said relay extending from the relay at the manual end of the trunk to the third or test contact thereof at the first exchange, means at the automatic exchange for energizing said relay over said circuit when connection is of 105 110 115
77. In a telephone exchange system, an automatic exchange and a manual exchange with a trunk line extending between a pair of contact terminals and a test terminal for the trunk in the banks of an automatic switch at the first exchange, a manually operated terminal for the trunk at the second exchange, an advance signal associated with said manual terminal, a relay controlling said signal, a circuit for said relay extending from the relay at the manual end of the trunk to the third or test contact thereof at the first exchange, means at the automatic exchange for energizing said relay over said circuit when connection is of 110 115 120
78. In a telephone exchange system, an automatic exchange and a manual exchange with a trunk line extending between a pair of contact terminals and a test terminal for the trunk in the banks of an automatic switch at the first exchange, a manually operated terminal for the trunk at the second exchange, an advance signal associated with said manual terminal, a relay controlling said signal, a circuit for said relay extending from the relay at the manual end of the trunk to the third or test contact thereof at the first exchange, means at the automatic exchange for energizing said relay over said circuit when connection is of 115 120 125
79. In a telephone exchange system, an automatic exchange and a manual exchange with a trunk line extending between a pair of contact terminals and a test terminal for the trunk in the banks of an automatic switch at the first exchange, a manually operated terminal for the trunk at the second exchange, an advance signal associated with said manual terminal, a relay controlling said signal, a circuit for said relay extending from the relay at the manual end of the trunk to the third or test contact thereof at the first exchange, means at the automatic exchange for energizing said relay over said circuit when connection is of 120 125 130

fected with the trunk, and means associated with the manually operated terminal for disabling said signal while said terminal is in use.

- 5 71. In a telephone exchange system, an automatic exchange and a manual exchange with a trunk line extending between them, a pair of contact terminals and a test terminal for the trunk in the banks of an automatic switch at the first exchange, a manually operated terminal for the trunk at the second exchange, an advance signal associated with said manual terminal, a relay controlling said signal, a circuit for said relay extending from the manual end of the trunk to the third or test contact thereof at the first exchange, means at the automatic exchange for energizing said relay over said circuit when connection is effected with the 10 trunk, and means associated with the manually operated terminal for disabling said signal while said terminal is in use.

72. In a telephone exchange system, an automatic exchange and a manual exchange with a trunk line extending between them, a selective switch in the automatic exchange containing bank terminals of the trunk line, a terminal plug for the trunk at the manual exchange, and a pair of relays associated 15 with said plug, line jacks adapted to cooperate with the plug, a pair of signals also associated with the plug, an energizing circuit for the first relay completed through the banks of the said selective switch, an 20 energizing circuit for the second relay controlled in the use of the terminal plug, contacts in the first relay controlling one of said signals, contacts in the second relay controlling the energizing circuit of the first 25 relay, other contacts in the second relay controlling the circuit of the first signal, and contacts in the trunk plug and the co-operating line jacks, included in circuit with the second signal, whereby the connection of a 30 switch to the trunk will energize the first relay and display the first signal, and the insertion of the trunk plug in a jack thereafter will energize the second relay, shift the connection of the first relay, and display 35 the second signal, at the same time retiring the first signal.

73. In a telephone exchange system, an automatic exchange and a manual exchange with a trunk line extending between them, a 40 selective switch in the automatic exchange containing bank terminals of the trunk line, a terminal plug for the trunk at the manual exchange, and a pair of relays associated 45 with said plug, line jacks adapted to co-operate with the plug, a pair of signals also associated with the plug, an energizing circuit for the first relay completed through the banks of the said selective switch, an energizing circuit for the second relay controlled in the use of the terminal plug, con-

tacts in the first relay controlling one of said signals, contacts in the second relay controlling the energizing circuit of the first relay, other contacts in the second relay controlling the circuit of the first signal, and contacts in the trunk plug and the co-operating line jacks, included in circuit with the second signal, together with locking contacts in the first relay closed when the relay is energized so as to connect its windings directly across the trunk for self-sustained connection therewith so long as the switch connection remains established.

74. In a telephone exchange system, line circuits, link circuits for interconnecting the same, a primary selector switch for each link circuit containing calling terminals of the lines, an operator's circuit, a secondary selector switch adapted to connect the operator's circuit to a link circuit simultaneously with the connection of the link circuit to a line, actuating means for the primary selector, a cut-on relay therefor, a controlling circuit for the secondary selector including contacts in said cut-on relay, a self-locking circuit for the cut-on relay closed at one point when it is energized, a link relay energized when the link becomes connected to a line, and acting when energized to open the cut-on relay at a second point, a controlling relay associated with the link and containing normally closed contacts included in the locking circuit of the cut-on relay at a third point, and means associated with the secondary switch and the operator's circuit to energize said controlling relay when the secondary selector switch becomes connected to the link, whereby the continuity of the control circuit from the link to the secondary selector and operator's circuit is maintained until the secondary selector switch is connected with the link, irrespective of the time of connection of the primary selector switch with the calling line.

75. In a telephone exchange system, line circuits, link circuits for interconnecting the same, automatic selector switches associated with the links, including primary selector switches for connecting calling lines to the links, an operator's circuit and a secondary selector switch adapted to connect the same with any one of a plurality of links, means for starting a primary selector switch and a secondary selector switch and for driving them simultaneously to a calling line and to the selected link respectively, a relay energized in the starting of the primary selector switch and circuit connections therefrom controlling the movement of the secondary selector switch, a locking circuit for said relay and a controlling relay for said locking circuit associated with the primary selector switch a circuit for said controlling relay extending to the secondary selector switch and means associated with said switch and

automatically controlled in the operation thereof to maintain the energization of the first relay in the primary selector switch until the completion of the operation of the 5 secondary selector switch.

76. In a telephone exchange system, line circuits and link circuits for interconnecting the same, primary selector switches for connecting the links with calling lines, talking contacts and test contacts in the said primary selector switches, a source of current supply for the talking circuits, a relay associated with each link in the path of talking current from said link to the source, test 10 connections from said relay, and means becoming operative through the actuation of the primary selector switch to shift the connection of said relay to the test wiper of the switch for the purpose of testing line 15 contacts, and thereafter when the calling line is connected to shift the same to its normal connection between the source of current supply and a link conductor.

77. In a telephone exchange system, line 20 circuits, link circuits for interconnecting the same, primary selector switches for connecting the links to calling lines, and controlling means for each primary selector switch comprising the following instrumentalities: 25 actuating magnets and energizing means therefor, a controlling relay for the same, a pair of talking wipers connected to the talking conductors of the link, and an associated test wiper adapted to sweep over test 30 contacts associated with the respective line talking contacts in the switch banks, line controlled relays for establishing a busy test condition on said line test contacts, tip and sleeve relays for the link, a source of current 35 supply for the relays and for the talking circuit including the subscribers' transmitters, and a cut-on relay for the actuating 40 magnets containing contacts included in the circuits of the tip and sleeve relays adapted 45 while the switch is operating to break the circuit of the tip relay, and to connect the sleeve relay between the source of current and the test wiper, together with contacts in 50 said sleeve relay controlling the circuit of the cut-on relay, whereby when the switch is 55 started in response to a call, the cut-on relay being energized will maintain continuity of operation of the actuating magnets until the sleeve relay acting as a test relay is brought 60 into connection through the wiper with the charged contact of the calling line, and the consequent energization of the sleeve relay will deenergize the cut-on relay, thereby shifting its contacts to disconnect the sleeve 65 relay from the test wiper and complete the connection of both the tip and sleeve relays to their respective link conductors.

78. In a telephone exchange system, line 70 circuits and link circuits for interconnecting them, primary selector testing switches for

the link circuits, adapted to test for and connect calling lines to their respective links, battery supply relays for each link, and means associated with each link for switching a battery supply relay into testing relation with its primary selector switch until the calling line is found, and means then becoming operative to shift said relay to its normal connection and stop the switch in connection with said calling line. 75

79. In a telephone exchange system, line circuits and automatic switches for interconnecting the same including selector switches containing groups of trunk terminals for percentage selection, an operator's circuit 80 with means to connect it to said switches, a sending machine associated with said operator's circuit and means for transmitting from said sending machine to said selector switches successive groups of impulses, consisting alternatively of directive number groups adapted to drive the selector switches to predetermined groups of trunks, and constant groups of ten impulses each adapted to impel a selector switch indeterminately over 85 the trunks in any selected group, for the selection of an idle trunk therein.

80. In a telephone exchange system, line circuits and central office automatic switching equipment for interconnecting the same including selector switches containing trunk terminals in segregated groups for percentage selection, and means at the central office adapted to supply impulses for said switches in alternate groups of variables and invariables, with means to predetermine the number of the variable impulses in any group so as to drive a selector switch to a corresponding group of trunks, and means thereafter operative to permit the transmission of the 90 invariable group of impulses to drive the switch in advancing.

81. In a telephone exchange system, line circuits, including a line serving a plurality of substations, automatic switches for interconnecting the lines including selector and connector switches, party-line selective ringing apparatus associated with the connector switches and adapted to be set therethrough, an operator's circuit and switching means 110 for interconnecting the same to any one of a plurality of selector switches, means associated with the operator's circuit for actuating said selector switches when so connected, and means for making reverting calls over the party-line or lines comprising a special selector switch permanently associated with the operator's circuit but normally disabled, means for rendering the same active in response to a reverting call and at the same time disabling the operator's circuit for connection with any other selector switch, connector trunk terminals in said special selector switch, means in each connector circuit 115 for exclusive control of the connector switch 120

125

130

by the subscriber or subscribers on the party line, and means for restoring the special selector switch after a reverting call connection has been established, leaving only the connector switch associated with the calling called line.

82. In a semi-automatic telephone exchange system, selector and connector switches, an operator's circuit and a secondary selector responsive to calls to connect the operator with selector trunks when brought into service, means for releasing said secondary selector switch when a connection is established, a special first selector switch permanently connected with the operator's circuit and containing multiples of the same circuits represented in the ordinary first selector switches, a master switch under control of the operator having contacts normally disabling the special first selector and rendering active the secondary selector switch but adapted to disable the secondary selector and render active the special first selector for reverting calls at will.

83. In a semi-automatic telephone exchange system, selector and connector switches, an operator's circuit and a secondary selector responsive to calls to connect the operator with selector trunks when brought into service, means for releasing said secondary selector switch when a connection is established, a special first selector switch permanently connected with the operator's circuit and containing multiples of the same circuits represented in the ordinary first selector switches, a master switch under control of the operator having contacts normally disabling the special first selector and rendering active the secondary selector switch but adapted to disable the secondary selector and render active the special first selector for reverting calls at will.

84. In a semi-automatic telephone exchange system, line circuits, primary selector, secondary selector, first selector, and connector switches, with means whereby a calling subscriber may produce actuation of the primary and secondary selector switches to connect his line to an operator's circuit, special switching means associated with said operator's circuit affording access to connector switches independently of the secondary selector switches, and means adapted to release the primary and secondary selector switches when the operator's special selector is brought into service, whereby a called party-line which is also the calling party-line may be supplied with ringing and talking current from a connector switch alone, without tying up any other central office trunks or switches.

85. In a telephone exchange system, line

circuits, link circuits for interconnecting the same, primary selector switches for connecting calling lines with said links, an operator's circuit, a secondary selector switch responsive to calls to connect the operator's circuit with a link when brought into a connection with a calling line, a primary distributing switch, means responsive to current flowing in calling lines to actuate said distributing switch, means controlled by said switch for rendering and maintaining only one link at a time in active condition for line selection, and means in the link circuit and coöperating means in the operator's circuit adapted to maintain said distributing switch locked in relation with an active link until the operator's circuit has become connected to said link and said link has become connected to the calling line.

86. In a telephone exchange system, line circuits, link circuits for interconnecting the same, a primary selector switch for each link circuit, adapted to connect its link to calling lines, a plurality of operators' circuits with secondary selector switches containing multiple terminals of the links, means for selecting an idle link circuit for connection with a calling line, a plurality of means for selecting an idle operator's circuit for connection with a selected link and therethrough with the calling line, and means actuated in the first movement of the secondary selector switch of the selected operator's circuit, adapted to produce a busy test in all of said operator's selecting means in response to any calls for selection thereafter while the operator's circuit is in use.

87. In a telephone exchange system, line circuits, link circuits for interconnecting the same, primary selector switches for the links containing talking terminals and test terminals for the lines, and talking and test wipers coöperating therewith for the links, a plurality of operators' circuits each having a secondary selector switch containing test terminals and talking terminals for the links, and talking and test wipers for the operator's circuit, primary distributing switches containing test terminals connected with control circuits in the several links, secondary distributing switches containing test terminals connected with control circuits associated with the several operators' circuits, and contacts controlled in the first movement of each secondary selector switch adapted to produce a test condition on the corresponding terminals in the secondary distributing switches, whereby the associated operator's circuit is rendered immune from selection as long as it is in use.

88. In a telephone system, in combination with means for producing impulses, a step-by-step selecting switch adapted to be connected to said impulse-producing means, means for determining the number of im-

pulses to be transmitted and a second step-by-step switch for controlling the connection of said impulse-producing means to the first step-by-step switch.

- 5 89. In a telephone system, in combination, a plurality of line circuits, switching mechanism for interconnecting the lines, means for actuating said switching mechanism, comprising means for producing
10 groups of impulses in recurring cycles, a step-by-step switch actuated one step for

each cycle and adapted to change the connection of said impulse-producing means to the switching mechanism for interconnecting the lines, and means for controlling the 15 impulse-producing means.

In testimony whereof I affix my signature in presence of two witnesses.

JOSEPH L. WRIGHT.
